UNITED STATES PATENT OFFICE.

CHARLES F. PYM, OF LYNN, MASSACHUSETTS, ASSIGNEE, BY MESNE ASSIGNMENTS,
TO UNITED SHOE MACHINERY CORPORATION, OF PATERSON, NEW JERSEY, A COR-
PORATION OF NEW JERSEY.

LASTING MACHINE.

1,413,613.

Specification of Letters Patent. Patented Apr. 25, 1922.

Application filed February 1, 1917. Serial No. 146,028.

To all whom it may concern:

Be it known that I, CHARLES F. PYM, a subject of the King of Great Britain, residing in Lynn, in the county of Essex and 5 State of Massachusetts, have invented certain Improvements in Lasting Machines, of which the following description, in connection with the accompanying drawings, is a specification, like reference characters on 10 the drawings indicating like parts in the several figures.

This invention relates to the shaping of shoe upper materials, and in some of its important aspects to lasting machines of the 15 type designed to operate upon shoe uppers to shape the uppers to the ends of their lasts and to wipe them over the edges of the soles on the last bottoms, the term "sole" being used herein for convenience to designate 20 the shoe part to which the upper is secured in lasting and thus embracing in its scope the insole of certain types of shoes. In one aspect, an object of the present invention is to provide a lasting machine which 25 will effect the lasting operation in an expeditious and thorough manner without requiring a high degree of skill on the part of the operator and which is adapted for adjustment to accommodate the mechanisms 30 to various shapes and sizes of lasts whose ends are to be operated upon.

A feature of the invention consists in a novel combination and arrangement of means for pulling or stretching the upper 35 at one end of the last outwardly against the edges of end embracing wipers and for causing the wipers subsequently to draw the stretched upper against the end of the last and fold it over the edge of the sole on the 40 last bottom without pressure of the wipers against the lateral periphery of the last. Preferably, the outdrawn and stretched upper is maintained under tension during the closing movement of the wipers or at least 45 until the wipers advance over and press the upper down upon the edge of the sole.

This manner of shaping or forming the upper to the end of the last and over the edge of the sole on the last is particularly 50 advantageous for lasting the toes of turn shoes in that there is no upwiping pressure of the wipers against the lower edge of the sole within the upper, which sole, in

the inside out condition in which turn shoes are lasted, forms a ridge which may be encountered by the upwiping wipers to the damage of the shoe. The mechanism provided by the present invention conforms the upper to the end of the last by the outdraw of the upper and by the subsequent closing 60 of the wipers approximately in the plane of the sole with the upper stretched and preferably tensioned, so that the stretching and conforming advantage of the upwipe is secured without its objectionable features. 65

The stretching and conforming of the upper materials is greatly facilitated by laterally outdrawing and foredrawing the upper against and over the inner edges of the wipers which are maintained substantially 70 in open position remote from the last during this operation. In accordance with a further feature of the invention a relative movement of the last and the wipers in a direction transverse to the plane of the last 75 bottom is effected while the upper is held outwardly away from the lateral periphery of the last and in engagement with the edges of the wipers in order further to stretch the upper and to render the wipers effective 80 with a substantial wiping action over a portion of the upper before the work is disposed in the proper relation to the wipers to permit the overwiping operation to be performed. The inner edges of the wipers act 85 as ironing bars to eliminate the wrinkles and as tensioning bars to stretch the upper and coincidentally to eliminate the wrinkles and other inequalities during such relative movement of the last and wipers to position the wipers and shoe sole in approximately 90 the same plane for the wiping over operation.

The elimination of the wrinkles and the stretching of the upper in this manner is of 95 particular advantage in lasting toes. In the case of turn shoes, the lining, which is on the outside during the lasting, directly engages the ironing out and stretching edge of the wipers and is more fully stretched 100 and more tightly lasted than the upper leather. When the toe is turned subsequently for the re-lasting operation, the lining will fit snugly and closely to the inside of the toe while the leather may be 105 further stretched to enclose the lining. Ob-

viously, with welt and McKay toes, the leather of the upper is on the outside and directly engages the wiper edges and receives the relatively greater stretching and 5 conforming pull which is the action required for these classes of shoes.

In lasting the toe ends of shoes, the last and shoe come to the operator with the upper temporarily held on the last in proper 10 position by tacks, usually inserted by a "pulling over" machine which secures the upper to the sole substantially at the tip seam and at the extreme end of the toe. The end tack is removed in lasting the toe, but 15 the tip seam tacks usually remain. In out-drawing the upper preparatory to wiping it over the end of the toe, as heretofore practised, the direction of outdrawing movement has often exerted such lateral 20 strain upon the upper at the tip seam that the pulling over tacks and the upper have been loosened at this point, with the result that the upper subsequently shifts during the toe lasting operation with the obvious 25 result of spoiling this operation.

A feature of the present invention resides in a novel construction and arrangement of grippers and operating means designed to avoid the above-mentioned consequences; the 30 construction shown comprising grippers for engaging the edge of the upper at opposite sides substantially at the corners of the toe and means to swing the grippers laterally outward from the sides of the toe 35 in curved paths effective to secure a diagonally forward outdraw on the upper at the corners of the toe with minimum outdraw,—practically only foredraw,—on the upper rearwardly of the corners, so that 40 there is no substantial outward pull on the upper at the tip seam such as to loosen the securing tacks at this point.

A further feature of the invention consists in a novel construction and arrangement 45 affording provision for adjustment of the grippers, the illustrative embodiment comprising grippers positioned above the wipers on the machine and arranged to grip the edge of the upper at the opposite sides 50 of one end of the last, with means for bodily adjusting the grippers toward and from each other transversely of the last and with means for angularly adjusting the grippers about axes substantially perpendicular to 55 the last bottom. Preferably, the transverse and angular adjustment of the opposed side grippers is independently effected, so that their positions may be varied for rights and lefts. In the machine illustrated, also, a 60 gripper for the extreme end of the upper is employed in conjunction with the side grippers, this end gripper in the construction shown, as to adjustment, being stationary relatively to the side grippers.

65 Generally speaking, the curvature of the

toe end of a last is formed of an end curve at the extreme end and of two side curves joining the end curve substantially at the forward ends of the corners of the last. The side grippers, which are herein shown 70 as located at the corners of the last, are angularly adjustable in the construction shown about vertical axes substantially coincident with their forward ends, so that the grippers may not only have transverse 75 adjustment for width, but may also have this angular adjustment about the points of junction of the side and end curves of the toe.

A further feature of the invention consists in a novel construction and arrangement for determining the proper position of the work in the machine, the construction shown comprising a gage member arranged to engage the feather of the sole at the toe 80 end of the shoe and positioned in such relation to the grippers and the wipers as to determine the initial position of the shoe relatively to these parts when the shoe is presented. In the illustrative construction, 85 moreover, this feather engaging member serves also to maintain the marginal edge of the sole in the correct relation to the bottom of the last.

In presenting shoe uppers to lasting machines in which grippers or pincers grasp the upper material and stretch it outwardly, it is not only desirable that the shoe upper be initially positioned to co-operate with the grippers, but it is also desirable that the 100 movable jaw of the grippers, in closing upon the upper, shall gather all of the upper materials against the fixed jaw. A feature of this invention consists in a novel organization including wiper mechanism and last 105 and shoe supporting and positioning means, with upper gripping mechanism including a gripper jaw having an outreaching component of movement which changes to an inward component toward the end of the gripping stroke so that the movable jaw reaches out and over the upper materials and then gathers them in towards and against the fixed jaw of the gripper.

In wiping the upper over the edge of the 115 sole it is necessary to successful lasting that the edge of the upper be compacted down on the edge of the sole. The pressure which is necessary to accomplish this result is, of necessity, exerted in a direction which is substantially perpendicular to the plane of the last or sole bottom and causes the wipers, in advancing over the sole, to exert a forward thrust against the last and sole in a lengthwise direction, tending to displace the last or sole, or both, lengthwise. A feature of the present invention consists in a novel organization comprising opposed members relatively movable to clamp a last with its sole 125 and shoe upper between them, with means 130

operative to cause one of these members to exert compacting pressure against the wipers in a direction as stated and to cause the other of said members to hold the last and shoe against lengthwise displacement. As previously practised, a backing or stop member, additional to clamping means, has been provided for the opposite end of the shoe.

The invention also provides a novel method of treating upper materials, having in view, in one important aspect, the advantages of "upwiping" the upper without danger of displacing the edge of the sole or of otherwise injuring the shoe materials, and in a further aspect having in view the pulling of the upper at the toe in such manner as to avoid displacing the upper materials at the rear of the corners of the toe.

The invention will now be more particularly described by reference to the accompanying drawings, which show a machine adapted to carry out the novel method and in which the novel features of the invention are embodied.

25 In the drawings:—

Fig. 1 is a view in side elevation of the assembled machine, the parts being in the position of rest prior to the starting of the cycle of operations;

30 Fig. 2 is a front elevation on an enlarged scale of the upper part of the machine;

Fig. 3 is a fragmentary plan view of the gripper adjusting and operating mechanism;

35 Fig. 4 is a plan view, partly in section, of the wiper mechanism and its operating connections;

Fig. 5 is a plan view, on an enlarged scale, of the cam shaft, cams, and driving shaft; Fig. 6 is an elevation, partly in section, of 40 the jack, holddown and sole positioning means;

Fig. 7 is a perspective view of said parts with their operating cams and connections;

45 Fig. 8 is a side elevation of the peripheral jack cam and its motion transmitting roll, the pincer closing cam groove in the opposite face of the cam disk and the connecting roll and lever being shown in dotted lines;

Fig. 9 is a side elevation of the holddown 50 controlling peripheral cam with its operating lever and of the wiper operating cam groove in the face of the cam disk;

Fig. 10 is a side elevation of the sole toe 55 presser peripheral cam with its operating lever and of the pincer-swinging cam groove in the face of the cam disk;

Fig. 11 is a vertical section on an enlarged scale of a pincer mechanism;

60 Fig. 12 is a fragmentary vertical section showing the holddown, jack, sole positioning finger, and grippers in their relative positions with the grippers closed and the last positioned with the sole above the wipers prior to depression of the last;

65 Fig. 13 is a view of the same parts with

the last depressed to updraw the upper and to aline the sole and wipers, and with the grippers laterally outdrawn and foredrawn to stretch the upper against and over the edges of the open wipers;

70 Fig. 14 is a plot of the cams for controlling the wipers, jack, holddown, grippers or pincers and sole control or gage finger, the cam paths being plotted throughout a complete cycle of twenty periods of 18° 75 each.

A hollow pedestal 2 has its open cylindrical upper end longitudinally split and connected by suitable clamping bolts 4 (Fig. 1). The cylindrical neck 6 of a head 8 is vertically adjustable in the upper end of the pedestal in setting up the machine by means of adjusting screws 10 swiveled in off-sets in the head and having threaded engagement with bores in alined ears 12 offset from 80 opposite sides of the pedestal at its upper extremity. When the head 8 is adjusted to the desired elevation, it is clamped in position by tightening the bolts 4. The head 8 is crowned by spaced frames 14 85 bolted to the top of the head and housing or supporting the mechanism of the machine between them.

90 A jack cylinder 18 is guided for vertical movement by a guide sleeve 20 at the forward end of a bracket 22 secured to the front of the pedestal and is supported and variably positioned vertically by a lever 24 extending rearwardly through the head 8 and journaled on a spindle 26 supported 100 from said head 8. The forward end of this lever is bifurcated and is notched to receive pins laterally outstanding from opposite sides of the square upper end of the cylinder 18.

105 The lower end of the cylinder is internally threaded to receive a centrally bored and exteriorly threaded plug 28 through which extends the lower end of a rod 30 whose upper end extends up through a bore 110 in the upper end of the cylinder and through a guide sleeve 32 at the forward end of a bracket 34 attached to head 8. The upper end of the rod is formed with a longitudinal slot therein with which the inner end of a pin 36 in the sleeve 32 cooperates to prevent the rod from turning about its longitudinal axis. The upper end of rod 30 carries a toe rest 38 suitably formed and preferably covered with leather 115 or other suitable material to prevent injury to the toe of the shoe. Since the machine is capable of operating upon the heel ends of shoes, it will be obvious that a last pin may be substituted for the toe rest.

120 Within the jack cylinder 18 a coiled spring 40 is housed, its opposite ends abutting against the upper end of the screw plug 28 and a collar 42, fixed to the rod 30 at 125 the upper end of the cylinder. This jack 130

- spring normally tends to hold the shoe supporting rod 30 elevated with the collar 42 engaging the upper end of the cylinder.
- 5 Mounted in bearings at the rear of the head 8 is a drive shaft 44 having one end extended out beyond the head and carrying for free turning movement a power-driven pulley 46 whose inner face is cupped to form one member of a cone clutch 10 the other member of which is in the form of a clutch disk 48 keyed to and sliding on the shaft 44 and normally held out of engagement with the pulley by suitable springs (Fig. 5). The clutch disk 48 has 15 a sleeve portion keyed to the shaft with its inner end abutting a block 50 mounted on the shaft and having an inner wedge face (Fig. 2). A clutch operating bar 52 is suitably guided for vertical movement and 20 is provided intermediate of its ends with a yoke portion 53 embracing and guiding on the shaft and having a beveled face to engage the wedge face of block 50. The slot of this yoke portion is elongated to 25 permit its beveled face to move vertically toward and from the beveled face of block 50. The upper end of the bar 52 is slotted and guides on a cam shaft positioned immediately above the drive shaft 44.
- 30 The bar 52 is normally raised to place the high point of its beveled yoke face above the block by means of a coiled spring 54 sleeved on a treadle rod 56 between a bracket secured to the head 8 and a washer abutting 35 the base of a hook at the extreme upper end of the rod, which hook engages a pin laterally offset from the lower end of bar 52. The lower end of the rod extends freely through a bore in the rear end of 40 a lever 58 and is threaded to receive an adjustable abutment nut engaged by said lever when moved downwardly by depression of a treadle 60 connected to the forward end of said lever by the bent link 62.
- 45 The wedge block 50 is prevented from turning on the shaft 44 by a pin projecting from the yoke 53 and entering in a vertical slot in a tail piece depending from the wedge block.
- 50 Depression of the treadle causes downward movement of bar 52, bringing the high portion of the beveled face of its yoke portion downwardly against the face of the wedge block and moving said block toward 55 the pulley to force the clutch disk 48 into frictional clutching engagement with the pulley.
- This clutching position of the parts is maintained against the tension of the clutch 60 and treadle rod springs for a period predetermined by the location of notches in the peripheral edge of a stop disk 64 carried by and rotating with a cam shaft 66 journaled in the frame 14 above and substantially in 65 vertical alinement with the driving shaft
44. The portion of the bar 52 extending upwardly from shaft 44 carries a roll 68 normally pressed against the periphery of the stop disk by the treadle rod spring 54. The extreme upper end of the bar is slotted to embrace and guide upon the cam shaft 66. When the roll is permitted to enter a notch in the peripheral edge of the stop disk, the high portion of the beveled face of yoke 53 is located above and out of clutch 70 operating position relatively to the wedge block 50.
- When the treadle 60 is operated the clutch is operated and since the cam shaft is driven through the drive shaft 44 as later explained, 80 the notch in the stop disk will be moved away from the roll and the higher peripheral edge of the disk will hold the roll and bar depressed into clutching position until the next notch in the stop disk comes 85 opposite to the roll, whereupon the spring 54 will move the bar upwardly out of clutching position and will force its roll into the notch of the stop disk, automatically halting the operation of the machine. 90
- The cam shaft 66 is driven from the drive shaft 44 through the following train of mechanism. On the drive shaft within the frame 8 is mounted a pinion 70 (Fig. 2) meshing with a gear 72 (Figs. 1 and 5) mounted on a counter shaft 74 journaled in brackets extending rearwardly and downwardly from the rear ends of the frames 14. This counter shaft carries a second and smaller gear 76 (Fig. 5) spaced from the 100 first gear laterally of the frame and meshing with a gear 78 mounted upon the cam shaft 66. The cam shaft, at the side upon which the pulley 46 is located is extended outwardly from the frame 14 to receive and 105 position the stop disk 64 with its peripheral edge alined with the roll 68 of the clutch operating bar.
- Within and between the frames 14, a series of cams are keyed upon the shaft 66 and are 110 constructed and arranged to control and operate the previously described last jack, and certain wiper, pincer, holdown and toe presser mechanisms later to be described. As shown, (Figs. 4, 5 and 7), two peripheral 115 cam disks 80 and 82 are keyed on the cam shaft and preferably have their faces contacting, the disk 80 having an integral sleeve 84 to space said disk from the next adjacent cam disk, later to be described, so 120 as to permit the entry of actuating arms between the spaced disks for co-operation with cam grooves in the adjacent faces of the spaced disks.
- The cam disks 80, 82 are keyed to the cam shaft in determinate relation and have cam grooves 86, 88, formed in their respective outer faces. Keyed to the cam shaft with its inner face abutting the sleeve 84 is a 125 peripheral cam disk 90 having a cam groove 130

92 formed in its inner face which is spaced from the adjacent face of cam disk 80 by the sleeve 84. The inner face of the gear 78 may, and as shown, does abut the outer 5 face of the cam disk 90 which is keyed therewith to the cam shaft 66 with its cams in determinate relation to those of cam disks 80 and 82.

A web 141 (Fig. 4) connecting the side 10 frames 14 is formed with a central bore lengthwise of the machine to receive the neck 94 of a wiper head 96, which is guided for reciprocation in said web and prevented from turning by a key 98. The neck 94 is formed 15 with a bore 100 in its rear end in which the reduced end 102 of a plunger rod 106 is inserted, said plunger which is preferably square in cross section, having its end turned down for insertion in bore 100, thereby 20 forming a shouldered portion 104 which bears against the rear end of the neck 94 when the rod end is inserted and rigidly attached, as by a driven taper pin 101.

The forward edge of the wiper head is 25 channeled to form a substantially semi-circular recess in which are seated wiper carrier plates 110 having their rear edges curved to conform to the curvature of the recess and toothed to form gear segments 112. This 30 recess provides upper and lower walls which confine the carrier plates against any vertical movement. Pivotaly interconnected wiper plates 114 having their outer edges curved to conform to the general contour 35 of the toe (or heel) ends of shoes to be operated upon, are seated in recesses formed in the forward edges of the carrier plates for independent relative movement automatically to adapt themselves to the contour 40 of the shoe end when they are closed upon the same. They are retained within the carrier plates by pins on these plates entering slots extending rearwardly from the forward edges of the wiper plates and curved upon 45 arcs concentric with the curved rear edges of the wiper plates. The upper and lower walls of the recesses in the carrier plates serve to confine the wiper plates against vertical movement.

50 The recess in the wiper head 96 and the toothed rear edges of the carrier plates 110 are formed on curves concentric with the pivot 116 of the wiper plates, the carrier plates being guided in said wiper head for 55 turning movement about the wiper pivot 116 as a center by means of rolls 118 carried by the head and positioned in slots 120 in the carrier plates, which slots are formed on arcs with the pivot 116 as a center.

60 The carrier plates with their supported wiper plates are designed to be turned through the bodily forward and rearward movements of the wiper head 96. Accordingly, on opposite sides and at the rear end 65 of the head, vertical gear spindles 122 are

journalized and carry in the plane of the carrier plates gears 124 meshing with the gear segments 112 on the rear edges of the carrier plates, and, in a plane above the gears 124, pinions 126 meshing with the teeth of 70 rack bars 128 extending lengthwise of the machine and having their forward ends guided in and projecting beyond the head 96 and their rear ends projected through and beyond and guided in channels in the 75 uprights of the frames 14. Preferably, the forward end of the wiper head is formed with open guide channels in which the forward ends of the rack bars 128 are seated, and in which they are retained by cover 80 plates 130 (Figs. 1 and 4), the rear ends of the bars being similarly retained in their guiding channels in the uprights of the frames 14. (Fig. 4).

The rear ends of the rack bars which project beyond the uprights of the frames 14 are rounded and threaded to receive tensioning nuts 132. Washers 136 are loosely seated over the threaded ends of the rack bars and abut against the rear faces of the frame 90 uprights. Between these washers and the tensioning nuts, coiled springs 134 are held and normally tend to move the rack bars rearwardly, this rearward movement being limited by stop pins 138 carried by the bars 95 and arranged to engage the front faces of the frame uprights, preventing rearward movement of the rack bars beyond this point.

The plunger 106 has its rear end extending 100 between the spaced cam disks 80 and 90 and is provided with a laterally offset roll entering into the cam groove 92 formed upon the inner face of the cam disk 90. This cam groove is formed to reciprocate 105 the plunger 106 in the manner later to be described, so as to effect a bodily reciprocation of the wiper head toward and from the end of a supported last and shoe. The springs 134 will hold the rack bars stationary 110 under normal conditions, so that as the wiper head is moved forwardly toward the shoe, the pinions 126 carried by the wiper head will travel over the rack bars, turning their spindles 122 and rotating their gears 115 124 to swing the carrier plates 110 and the wiper plates 114 about the wiper pivot 116 as a center, closing the wiper plates over the bottom of the last and the edge of the sole. As the wiper plates close into contact 120 with the shoe upper at the end of the last, these plates will automatically and independently adapt themselves to the contour of different right and left shapes of toes 125 through their pin and slot mounting in the carrier plates.

Should unusual resistance be encountered to the closing movement of the wiper plates as the head is projected forwardly, as, for example, by the resistance offered by unu- 130

sually stiff upstanding upper material, the 5 springs 134 may yield, permitting the rack bars bodily to move forwardly with the pinions 126 and wiper head, preventing thereby closing movement of the wiper plates until the resistance to closing movement becomes less than the adjusted tension of the springs 134.

Upon retracting movement of the wiper 10 head, the reverse action takes place, the wipers being swung outwardly from over the bottom of the last and sole when the stop pins 138 abut against the frame bars and prevent rearward yielding movement of the 15 rack bars 128.

The jack cylinder 18 with its last and shoe supporting rod 30, is raised and lowered in timed relation to the other mechanisms of the machine by contact of the 20 peripheral cam 80 with a roll 140 carried at the rear end of the jack operating lever 24. The adjacent spaced peripheral cam 90 is constructed and arranged to co-operate with and control a holddown member, between 25 which and the support 38 the last and shoe is clamped, the holddown engaging the face of the sole, holding it down upon the bottom of the last and at the same time clamping the last against the support 38 and in the 30 positions for co-operation with the various instrumentalities as will be later described. This holddown member is in the form of a foot 142 having prick points or teeth on its lower face and carried at the lower end of 35 a stem 144 guided for vertical movement and having its upper end reduced in diameter to extend through the threaded neck of a cup shaped member 146 (Figs. 6 and 7), whose neck is seated in a threaded bore in 40 a trunnion block 148. The upper extremity of the stem 144 is provided with a head fitting within the cup 146 and normally pressed downwardly by means of a coiled spring 150, whose tension may be varied 45 by a plug 152 screwing into the upper open end of the cup 146.

The trunnion block 148 is provided with pins outstanding from opposite sides and journaling in slots formed in the outer bifurcated end 154 of an operating lever 156 having a sleeve intermediate its ends journaling the lever on a spindle 158 supported between the frames 14. The rear end of this lever is provided with a roller 160 held by a coiled 55 spring 162 against the peripheral edge of the cam disk 90.

In wiping the edge of the upper over the edge of the sole, the wipers are liable to lift up and bend back the edge of the sole, in the 60 case of a turn shoe, unless it is held down until they have passed over the edge and have pressed the upper down over said edge. Accordingly, I have provided a sole controlling mechanism herein described and shown 65 as a feather edge toe presser foot 164 cres-

cent shaped in cross section to correspond substantially with the lip of the sole at the extreme end of the toe and designed to engage against the outer face of the lip of the sole when the shoe is positioned in co-operative 70 relation. This curved presser foot or sole control member is formed at the lower end of a stem 166 threading into a block 168, pivoted to the bifurcated forward end 170 of a controlling lever 172 which also has a sleeve intermediate its ends journaling on a spindle 174 supported by and between the frames 14 (Figs. 1, 2 and 7). The rear end of the controlling lever is laterally offset from its forward end (Fig. 7) and carries 80 a roll 176 positioned to rest upon the peripheral cam edge of the cam disk 82, mounted adjacent to the jack cam disk 80.

The pivoted block 168 to which the upper end of the toe presser foot is secured, has a 85 rearwardly extending and upwardly bent arm 180 to the rear and upper end of which is attached a rod 182 which extends downwardly and through an opening in a shelf 184 formed on the lever 172 adjacent to its 90 bifurcated forward end. A coiled spring is sleeved upon the rod 182 and normally tends to maintain the arm 180 elevated, and the presser foot 164 depressed but permits the presser foot to yield backwardly to avoid 95 breakage in case it receives abnormal pressure from the advancing wipers.

According to the present invention, it is proposed to conform the upper to the toe of the last by overwiping the upper while it is 100 in a stretched and tensioned condition. In order to accomplish this result most effectively it is proposed to grip the upstanding edges of the upper and by relative movement of the last and upper gripping means to up-draw, out-draw and fore-draw the gripped edge of the upper to stretch and center the upper, and to position and hold the upper under stretching tension for the wipers while they are advancing to wipe the upper over 110 on to the edge of the sole, thereby giving a very snug and close conformation of the upper materials to the last with all wrinkles and slack eliminated.

Accordingly, at a point above the wiper 115 head, a rectilinear frame 186 (Fig. 3) is attached to the front uprights of the frames 14 by means of laterally offset feet 188. Between its front and rear, the sides of the frame are connected by a web 190 having 120 a central enlargement 192 formed with a guide channel therein open at its top to receive the carrier bar 194 of an end pincer mechanism and closed by a cover plate 196. The front bar of the frame at opposite sides 125 is formed with transversely extending guide slots 198, closed at the front of the frame by cover plates 200 and is formed centrally with a tubular guide 202 for the stem 144 of the holddown, previously referred to. 130

This stem is formed with a vertical groove into which extends the smooth end of a set screw 204 carried by the tubular guide to prevent axial turning movement of the hold-down.

The laterally extended heads of pivot blocks 206 rest and guide on the top of the front frame bar at the front and rear sides of the guide slots 198, the blocks, below the bar, having rearwardly offset portions (Fig. 3) to the under side of which the forward ends of corner pincer supporting plates 208 are pivoted at 207. The pivot blocks 206 and the corner pincer supports, carriers and pincers may be adjusted bodily transversely of the machine to accommodate the corner pincers to different widths of toes by threaded spindles extending through the frame bars from the outer ends of the slots with their smooth inner ends journaling in the frame bars at the inner ends of the slots 198 and with their threaded shanks passing through threaded bores in the pivot blocks. Stop collars 212 on these spindles at the outer ends of the slots and their adjusting heads 214 at the ends of the frame bars prevent longitudinal movement of the spindles when turned, so that the pivot blocks may be adjusted longitudinally of the slots by manipulation of the knurled heads 214. The corner pincers or grippers may therefore be separately and bodily adjusted toward and from each other to provide for variance in the width of toes.

The supporting plates 208 for the corner pincers are in the form of segments, the outer edges of which are toothed and which adjacent to their inner edges, are formed with arcuate slots 216 having centers approximately coincident with the forward or toe ends of the corner pincers. These plates 208 support corner pincer carrying arms 218 which extend transversely of the supporting plates 208 and which have lateral extensions 220 intermediate of their ends. Rolls 221 depending from the arms and their extensions enter in and are guided by the slots 216 to permit the arms to swing relatively to their supporting plates 208 to effect swinging adjustment of the corner pincers supported from the inner ends of the arms 220 about axes substantially perpendicular to the plane of the last bottom and approximately in alignment with the forward or toe ends of the pincer jaws. In other words, the described construction permits independent angular adjustment of the corner pincers about vertical axes located at or near the ends of their jaws nearest the toe end of the shoe.

The outer ends of the arms 218 extend out beyond and overlie the toothed edges of the supporting plates and are provided with spring pressed manually releasable dogs 222 engaging the toothed edges to latch the pin-

cer carrying arms 218 in independently adjusted position relatively to their supporting plates 208. Obviously such an adjustment is desirable to meet variance in the contours of the toe ends of different styles of 70 shoes and the differences due to right and left toes.

In the position of rest of the machine, the end pincer supporting bar 194 with its pincer is positioned determinately and uniformly relatively to the sole controlling foot 164 which serves as a positioning gage for the shoe and last. This bar 194 is moved forwardly away from the last by power during the cycle of the machine to outdraw and 80 foredraw the upper at the extreme end of the toe coincidently with updraw resulting from depression of the last, and the corner pincer supporting plates 208 are coincidently swung outwardly from the opposite 85 sides of the last on their pivots 207.

This movement is effected by a plunger 224 extending through a guide 225 upstanding from a bracket 226 secured to a cross bar connecting the frames 14 near their rear, the 90 plunger forming a rigid forward extension of the end pincer supporting bar 194. Levers 228 extending transversely of the frame 186 are pivotally connected intermediate of their ends to bracket plates 230 depending from the side bars of frame 186 at their inner sides. The inner ends of the levers are pivoted to the under side of the supporting bar 194 by a pivot pin 232 and their outer ends are pivoted to abutment sleeves 234 100 mounted to slide on rods 236 and normally pressed against the headed adjacent ends of said rods by coiled springs 238 sleeved on said rods.

These rods adjacent to their opposite ends 105 are threaded and said ends adjustably engage in and project through threaded bores in ears 240 bolted to and depending from the corner pincer supporting plates 208 at their outer forward ends. The forward ends of 110 the springs 238 abut against tensioning nuts 242 on the threaded forward portion of the rods 236, which obviously may be adjusted to vary the tension of these springs.

Rearward movement of the plunger 224 115 will, therefore, move the end pincer support outwardly and forwardly of the toe and through the levers 228 and their yielding connections to the corner pincer supporting plates 208, swing these plates laterally outwardly from the opposite corners of the toe on their pivots 207. These pivots 207 are located rearwardly of those ends of the corner pincers nearest to the tip seam, as shown in Fig. 3, so that the upper is spread 120 laterally and diagonally outward in a direction forwardly of the toe with a comparatively small extent of movement at the ends of the pincers nearest the tip seam, so that there is no substantial lateral outward pull 125 130

against that portion of the upper at the tip seam which is held to the sole by the pulling over tacks. The upper at the tip seam is therefore not strained outwardly to such an extent as to pull these tacks from the sole and to pull the upper from the sole as has been the case when the outdraw has been applied as in prior constructions.

Rearward movement of other parts of the 10 plunger 224 is effected in timed relation to the cycle of operations by connections to the cam shaft 66. The rear end of the plunger which projects rearwardly beyond the 15 guide upstanding from bracket 226, is enlarged to form a block 244 (Fig. 3) from the opposite sides of which project pins 246 to which the bifurcated end of a rock arm 248 is pivotally connected (Figs. 1 and 3).

This rock arm is carried on and upstands 20 from a rock shaft 250 journaled in the bracket 226 and having a depending crank arm 252 (Fig. 1) to the lower end of which is pivoted the forward end of an actuating bar 254 having its rear end formed as a yoke 255 embracing and guiding on a collar on the cam shaft 66 and having a laterally offset roll seating in the cam groove 88 in the outer face of the cam disk 82, the peripheral cam face of which operates against the roll 25 30 176 and lever 172 to operate the sole controlling presser foot 164.

The end and corner pincers are similar in construction and each comprises a lower and stationary jaw 256 with its inner edge located 35 immediately over the wipers and substantially alined with the inner edges of the wipers as the wipers stand in open position. The gripping face of each lower jaw slopes upwardly and outwardly and has at its 40 outer end an upstanding shank portion 258 reduced in diameter at its upper end and extended up through and rigidly secured to the inner end of its carrier arm 218 or 194 by suitable means. Preferably, for convenience 45 in assembling, the jaw portions are formed separately from the shank portions and are rigidly secured thereto by a plurality of machine screws or other suitable securing means.

50 The shanks 258 are formed with vertical bores extending upwardly through their rounded upper ends, and below said bores, are channeled vertically and downwardly to their lower ends forming elongated slots 260 55 within the lower ends of which the jaw portions 256 are seated and held.

60 Reciprocating plungers 262 are seated in these vertical bores and extend downwardly into the slots 260, their lower ends having lateral offsets 268 projecting outwardly 65 through the slots 260 and having their ends pivotally connected to the upper ends of the shank portions of movable pincer jaws 264. These jaws intermediate their ends are pivotally supported from the fixed jaws by

links 266 of greater length than the offsets 268 and connected to the movable and fixed jaws at different distances from their lower extremities with the pivot points on the fixed jaws substantially removed, rearwardly, 70 from vertical alinement with the points of pivotal connection of the offsets 268 to the movable jaws 264. In raised position of the plungers the links 266 are inclined upwardly 75 from the horizontal so that downward closing movement of the movable jaw will include successive components of outward and inward movements.

On downward movement of the plungers, the offsets 268 and links 266 will move the 80 jaws 264 bodily downward and will coincidently swing the lower ends of these jaws outwardly until the pivots of each link are horizontally alined, and then as the outer pivots of the links 266 pass below the plane 85 of horizontal alinement the lower ends of the movable jaws will be abruptly swung inwardly, the inward component of movement supplanting the outward component toward the end of the clamping movement so that 90 the path of movement forms a hook-like curve with a sharp inward bend of the hook at the end of the movement. This action causes the jaws to reach out and gather in the lining and the upper and to draw them 95 toward and clamp them against the fixed jaws. Features of this pincer mechanism are claimed in a divisional application, Serial No. 423,538, filed on Nov. 12, 1920.

The fixed jaws in the position of rest of 100 the machine are located below the sole control foot with which the lip of the sole is engaged initially to position the shoe and are therefore positioned below the last bottom. When the last and shoe are manually 105 presented to and pressed against the positioning gage formed by the sole control foot 164, the upper and lining will usually enter between the fixed and movable jaws of the pincers by the mere presentation of the shoe 110 to the gage.

When the machine is started the pincers begin to close, the hold down and sole control foot moving downwardly and the last jack moving upwardly to clamp the last and sole between the toe support and the hold down with the edges of the lower pincer jaws slightly below the plane of the last bottom. The pincers are closed when the parts 115 reach this position and are thereafter moved outwardly to outdraw, foredraw, and stretch the upper as the last and shoe are moved downwardly as will be more fully explained.

120 The closing of the pincers is effected through the rotation of a cam on the cam shaft 66. The upper ends of the plungers 262 are pivotally connected by pins 270 to the lower ends of links 272 whose upper ends are pivotally connected to the lower ends of 130

- rods 276 by pivot pins 274 extending at right angles to the lower pivot pins 270 so that substantially universal adjusting movement of the pincers may be had.
- 5 Substantially spherical bearing members 278 are yieldingly supported on the rods 276 by coiled springs 282 sleeved on the rods 276 and having their lower ends abutting tensioning nuts 284 threaded on the rods 276,
- 10 said springs having their upper ends abutting flanges 280 formed at the lower ends of the spherical bearing members 278. The upper ends of these members seat in sockets formed in the under face of a plate 286
- 15 which with the members 278 provides ball and socket joints, the rods 276 above the tensioning nuts 284 being reduced in diameter and extending upwardly through vertical bores in the spherical bearing members and
- 20 through the plate 286, the upper face of which is coned out to permit play of the upper ends of these rods.
- Washers 277 fixed by set screws to the upper ends of these rods above the plate 286 hold the rods against downward movement relatively to the plate 286 while the springs 282 permit relative yielding movement between the plate, when moved downwardly, and the pincer closing rods, so that
- 25 the upper materials are gripped yieldingly by the pincers which will yield to prevent tearing of the upper and injurious strain upon the wipers. Obviously the tension of the springs 282, and the yielding point for
- 30 the pincer jaws, may be varied through the tensioning nuts 284.
- The plate 286, whose downward movement effects the closing of the pincers is formed by a lateral extension at the forward end of the upper arm 288 of a bell crank lever having a sleeve portion intermediate of its ends journaled on a spindle 290 supported by the side frames 14, and having its lower arm 292 extended downwardly between the spaced cam disks 80 and 90 and provided with a roll entering the cam groove 86 in the inner face of the cam disk 80.
- This roll is held against the outer wall of
- 50 the cam groove by the coiled spring 162 connected to the holdown lever 156 whose roller 160 bears against the peripheral cam on disk 90 so that the same spring holds the roll on lever 156 against the periphery of its cam 90 and holds the roll on arm 292 against the outer wall of the cam groove in the face of its cam disk 80. The roll 140 of the jack lever 24 is held against its cam periphery by the weight of the jack cylinder; the roll of the link 254 which effects
- 55 outrow of the pincers is held against the wall of its cam groove in cam disk 82 by the coiled springs 238 acting through levers 228, rod 224, etc.; and the roll 176 on the
- 60 rear end of the sole control lever 172 which engages the peripheral cam on disk 82 is held against the periphery of said disk by the spring 178 connected to arm 288 of the pincer closing bell crank lever, and serving to hold the roll on the rear end of
- 65 arm 292 of this bell crank lever against the wall of its cam groove similarly to spring 162.
- The cam disks 80, 82 and 90 which control and operate the jack, holdown, wipers, pincers and sole control are all keyed to the cam shaft 66 and their peripheral and groove cams are designed to operate their respective mechanisms in timed relation. In Figs. 5, 8, 9 and 10 I have illustrated the
- 70 various peripheral and groove cams with portions of their operating connections and in Fig. 14 the various cams are plotted so that their relative timing will be clearly apparent. This chart or cam plot is divided
- 75 into 20 periods or sections, each section representing movement of the cam through an arc of 18 degrees or one twentieth of a complete rotation of the cam shaft which constitutes in the present embodiment one cycle
- 80 of the machine. It will be understood that the relative timing shown constitutes a preferable arrangement but that it is susceptible of variation and adaptation within the spirit of the invention and within the scope of
- 85 the appended claims.
- With the described construction in mind, and with reference to the cam chart shown in Fig. 14, the sequence of operations and the action of the mechanisms is as follows,
- 90 it being understood that in the position of rest, the sole control foot and hold down are substantially above the toe rest 38 on the jack and also substantially above the plane of the wipers, with the fixed jaws of
- 95 the pincers substantially below the holdown and sole control foot and above the plane of the wipers as suggested in Fig. 2. The controlling cam for the sole control foot 164 as charted is figured for action with this
- 100 foot in substantial horizontal alinement with the holdown in the position of rest of the parts as seen in Figs. 6 and 7.
- The shoe upper to be lasted by a machine such as described usually comes to the operator with the upper assembled on the last and tacked at the heel end and with the sides and forepart pulled over the last and temporarily tacked to the insole at the tip seam and at the extremity of the toe. This
- 105 toe end tack, if one has been inserted, is removed by the operator and the end of a wire is anchored to a tack at the tip seam at one side, say, the left side, of the inverted shoe, the wire being then drawn across and over
- 110 the top of a substantially U-shaped guide plate 294 secured to the under face of the wiper head and projecting forwardly from said head, its ends being bent downwardly
- 115 to prevent injury to the operator by contact
- 120
- 125
- 130

with sharp edges. Preferably, the wire is drawn from a suitable spool 296 (Fig. 1) at the right side of the machine frame having suitable tensioning or braking means. The wire will be supported by said plate 294 rearwardly of and slightly below the operative edges of the wipers during the operation of the machine and at the proper time may be drawn around the toe to press the upper against the lip or shoulder of the sole and anchored to a tip seam lasting tack at the right hand side of the inverted toe to hold the wiped-over edge of the upper in the angle between the feather of the sole 10 and the face of the lip or shoulder.

When the wire has been anchored at one end and then drawn across the guide, the operator presents the toe of the inverted shoe and last to the sole control foot so that the outer face of the sole lip at the extreme tip 20 of the toe is engaged with the face of the curved sole control foot at its lower edge, the shoe and last usually being inclined upwardly toward said foot. If necessary the corner pincers are adjusted, prior to 25 presentation of the shoe, so that they will be positioned in line with the upstanding edge of the upper when the toe is presented to the sole control member.

30 The starting treadle 60 is now operated and the cam shaft is revolved through the first twelve periods of the cycle and partly through the 13th period when the notch 65 in the stop disk 64 alines with the roll 68 on the clutch operating bar 52 and causes the retraction of the clutch and the stopping of the machine in the middle of the 13th period of its cycle.

During the first three periods, the jack 40 cam raises the jack and toe support, and the holddown and sole control cams simultaneously lower the holddown and sole control foot, the last, shoe upper and sole being clamped between the holddown and toe rest 45 at the end of the third period, the holddown spring 150 being compressed and the trunnion block 148 engaging the shoulder of the holddown spindle so that the holddown exerts rigid clamping pressure on the sole and last, depressing the last and placing the jack 50 spring under tension. The holddown also levels the sole transversely and longitudinally into parallel relation to the wiper plane as established by the sole control foot. 55 During these movements and until the shoe is firmly clamped the operator maintains the lip of the sole against the sole control foot.

The act of presenting the shoe to the positioning gage formed by the sole control foot 60 will ordinarily position the edges of the upper between the fixed and movable jaws of the pincers. When this does not occur the edges may be inserted by pincers or similar means. As the machine is started, the movable jaws move downwardly and outwardly

and thence inwardly gathering the lining and upper and drawing it toward and clamping it against the fixed jaws of the pincers. The jaws will be fully closed before the end of the 3rd period beginning with which time 70 the pincer swinging cam becomes active, moving the end pincer straight rearwardly of the machine to foredraw and outdraw the upper and causing the corner pincers to move diagonally outwardly away from the toe end of the shoe, foredrawing and outdrawing the upper against and over the edges of the wipers which remain stationary during this outdrawing movement.

From the 4th period to the end of the 7th 80 the jack, holddown and sole control foot are lowering, causing the pincers to updraw the upper during the greater part of which time the pincer spreading cam is operating to foredraw and outdraw it in the directions 85 previously described. During the first upward movement of the jack, as previously described, the last and shoe are clamped between the jack and the holddown with the sole above the plane of the wipers and this 90 subsequent depression of the jack, holddown and sole control foot relatively to the pincers and wipers not only effects updraw on the upper, but the downward movement of the vertically rigid sole control foot locates the 95 sole slightly below the plane of the wipers, Fig. 13, the sole control foot not only serving to press the edge of the sole at the extreme end down on the last but functioning as a positioning gage at this phase of the 100 operation by placing the sole in the proper plane for overwiping movement of the wipers.

The upper is thus stretched upwardly and outwardly in a generally forward direction, 105 the edges of the wiper plates acting as a rigid bar over which said upper is stretched and tautened by the coincident updraw, foredraw, and outdraw. This action is particularly advantageous in lasting the toes of turn shoes, since the inside-out condition of a turn shoe with its extension sole inside of the upper makes it difficult, if not impossible, to stretch and conform the upper to the last by "upwiping" or relatively moving the 110 last and wipers with the wipers in last conforming contact with the sides of the shoe below the last bottom. In such cases the edge of the turn shoe extension sole forms a ridge in the upper about the toe, pressure 115 against which by the upwiping wipers will cause damage to the upper or to the edge of the sole, or to both. The present construction and operation stretches the upper and, as will be seen, wipes the stretched upper while under tension upwardly and then down over the edge of the sole without engaging the wipers with said ridge about the toe of the upper, making the construction 120 particularly advantageous for turn shoe 125 130

work, since it has the stretching and conforming advantage of an "upwipe" without its objectionable features.

During the latter part of the lowering movement of the jack, holddown and sole control foot, (beginning with the 6th period) the wiper cam becomes active and gradually moves the wiper head forwardly, gradually closing the wipers and as the last 10 lowers still further to the limit of downward movement, advancing them over the edge of the sole. The wipers will begin their advance over the edge of the sole during the first part of the 8th period, and 15 coincidentally, the sole control foot will be quickly raised out of the path of the wipers sufficiently far to clear them and will then be gradually raised to its original position, reaching this point at the end of the cycle. 20 The pincers reach the limit of their laterally outward movement approximately at the end of the 5th period and remain in such position for the 6th and substantially the 7th period, during which time the wipers 25 are closing, drawing and conforming the stretched upper to the toe of the last while tensioned by the pincers. The wipers reach the limit of their closing movement at the end of the 11th period, the pincers to a 30 very slight extent during the 7th period and more markedly during the 8th and 9th periods, moving inwardly toward the last with the wipers. Preferably, they are moved inwardly slightly beyond their original 35 positions to permit the wipers to force the upper into the angle between the sole lip and feather, this position of the pincers being reached in the 10th period and being maintained during the 11th period, after 40 which the pincers move very slightly outwardly to original position.

Should the upstanding edges of the upper be unusually short, or should the tension on the upper as the wipers close in, or at any 45 other time, be too great, the springs 282 of the movable jaws may yield to permit the upper to be pulled partially from between the closed pincer jaws. Ordinarily, closing of the wipers partially pulls the upper from 50 the closed pincers.

The pincers may safely move inwardly with the wipers after the wipers begin to advance over the edge of the sole without causing slack in the upper since the wipers hold 55 the upper down on the sole in stretched last-conforming position as soon as they advance over the sole edge.

From the 8th to the middle of the 11th period during which the wipers are moving to fully closed position, the jack is gradually lifted to exert through its spring, progressively increasing pressure against the wipers serving to compact the wiped over edges of the upper down upon the sole. During 65 this same period the holddown is gradu-

ally and proportionately raised by its cam to permit the pressure of the tensioned jack spring to be exerted against the wipers.

The movement of the holddown is effected through bodily upward movement of its 70 trunnion block so that at all times during this upward movement, the tension of the holddown spring is exerted against the sole and prevents longitudinal displacement of the sole and last by the closing thrust of 75 the wipers. The holddown spring, therefore, dispenses with the necessity for a back stop or heel clamp and additionally compensates for differences in the thickness of the last and insole clamped between the jack 80 toe rest and the holddown.

During the 12th period the wiper cam slightly retracts the wipers, the retracting movement reaching its limit in the middle of the 13th period, at which time the notch 85 65 in the stop disk 64 automatically arrests movement of the cam shaft, with the wipers partially retracted but still advanced over the edge of the insole.

During this retracting movement of the 90 wipers, the jack is slightly lowered by its cam, relieving the tension against the wipers to prevent "drag" on the wiped down edge of the upper, a sharp rise in the holddown cam coincidently acting to depress the hold- 95 down a corresponding distance, which distance is sufficient to position the bottom of the sole very slightly below the face of the wipers to permit the wire to be drawn through between the bottom of the wipers 100 and the bottom of the sole. This is the condition of the parts when the machine automatically comes to rest.

This rest or pause in the cycle permits the operator to draw in the wire carried on the 105 guide beneath the wiper head and to tighten it about the toe by drawing it in between the lower face of the wipers and the underlying sole and against the upper at the base of the sole lip at the toe, the end of the wire 110 being held temporarily under tension by the workman until the final wipe. This rest or automatic pause may be eliminated, however, since the operator may time himself to draw the wire into place at this point 115 in the machine cycle.

If the machine has been automatically stopped at this point, the clutch treadle is now operated to restart it. The jack is now lifted coincidently with the holddown, as in 120 the first wiping over movement, to press the upper against the wipers which coincidently advance, this time to a point slightly beyond the point of their first advance to force the wire tightly against the shoulder formed at 125 the base of the sole lip. This second wiping movement commences with the restarting of the machine in the middle of the 13th period, the wipers reaching the limit of their closing movement during the 15th period and there- 130

after beginning to retract, reaching fully opened position at the end of the cycle. As the wipers retract, the holdown lowers with the jack to relieve pressure against the 5 wipers and to return the holdown and jack to their respective original positions which they reach at the end of the cycle. The edges of the upper will ordinarily have been pulled from between the pincer jaws, 10 before or at least by the time the point of automatic stop is reached. As shown and plotted, the pincer closing cam becomes operative fully to open the pincer jaws toward the end of the cycle but it is obvious that 15 the opening point may be advanced substantially without interfering with the lasting operation.

As the wipers retract and the jack descends and the holdown ascends, the operator, grasping the shoe with the left hand and holding the wire under tension with his right hand, fastens it by twisting it around the side lasting or pulling over tack at the tip seam on the right side of the inverted 25 shoe, after which the shoe is removed from the toe rest and the wire cut at a point beyond the tack by any suitable means, such as shears 298 operated by a treadle 300, as seen in Fig. 1. This represents the completion 30 of the cycle of operations, the machine parts being ready for the next shoe to be lasted.

Having thus described my invention, what I claim as new and desire to secure by Letters Patent of the United States is:—

35 1. A machine of the class described having, in combination, end embracing wipers mounted for relative closing movement over a sole on a last at one end of the last, means to support and position a shoe on a last 40 with one end of its sole adjacent to and spaced from the inner edges of the wipers in open position, and power operated mechanism organized to pull and stretch the upper materials at said end of the last with a 45 component of outward movement to engage the upper with the edges of the wipers to maintain the wipers in substantially open position during such pulling movement and subsequently to advance and close the wipers 50 over the sole approximately in the plane of the sole.

2. A machine of the class described having, in combination, end embracing wipers mounted for relative closing movement over 55 a sole on a last at one end of the last, means to support and position a shoe on a last with one end of its sole adjacent to and spaced from the inner edges of the wipers in open position, and power operated mechanism organized to pull and stretch the upper materials at said end of the last with a component of outward movement to engage the upper with the edges of the wipers to maintain the wipers in substantially open position during such pulling movement, subse- 60

quently to advance and close the wipers over the sole substantially in the plane of the sole, and to maintain pulling and stretching tension on the upper materials as the wipers close over the edge of the sole on the last. 70

3. A machine of the class described having, in combination, end embracing wipers mounted for relative closing movement over an end of a sole on a last, means to grip the edge of the upper at the end of the last to 75 be operated upon by said wipers, means to support and position a shoe on a last with its end adjacent to and spaced from the inner edges of the open wipers and with said end of its sole in a plane removed from the plane of closing movement of the wipers, and power operated mechanism organized to close said gripping means on the edge of the upper and to cause said gripping means to updraw and outdraw the upper materials, 85 relatively to move the last and wipers approximately to align the sole with the plane of closing movement of the wipers while the edges of the wipers are in engagement with the upper, to maintain the wipers in substantially open position during such relative movements, and subsequently to advance and close the wipers over the sole approximately in the plane of the sole. 90

4. A machine of the class described having, in combination, end embracing wipers arranged to close over the bottom of a shoe sole at one end of a last and supported against movement perpendicularly to the bottom of the last, means to support and position a shoe on a last in co-operative relation to the wipers with the sole removed from the plane of the wipers and the end of the last and upper spaced from the inner edges of the open wipers, grippers positioned with their jaws in a plane removed from the plane of the wipers and arranged to engage the edge of the shoe upper at said end of the last, and power operated mechanism organized to operate said grippers to engage the upper, to depress the last to align the sole and wipers and coincidently to cause said grippers to updraw and outdraw the upper, to maintain the wipers in substantially open position during such updrawing and outdrawing of the upper and subsequently to close the wipers over the edge of the sole against the outward pull of the grippers to draw and conform the upper to the end of the last and to wipe it 115 over the edge of the sole. 120

5. A machine of the class described having, in combination, end embracing wipers arranged to close over the bottom of a shoe sole at one end of a last and supported against movement perpendicularly to the bottom of the last, means to support and position a shoe on a last in co-operative relation to the wipers with the sole removed from the plane of the wipers and the end of 125 130

the last and upper spaced from the inner edges of the open wipers, grippers positioned above the wipers and arranged to engage the edge of the shoe upper at said 5 end of the last, and power operated mechanism organized to operate said grippers to engage the upper to move the last approximately to aline the sole and wipers and coincidently to cause the grippers to updraw 10 and outdraw the upper, to maintain the wipers in substantially open position during such updraw and outdraw of the upper, subsequently to close the wipers over the edge of the sole, and to cause the grippers 15 to maintain the upper under outwardly stretched tension while the wipers close over the edge of the shoe sole.

6. A machine of the class described having, in combination, end embracing wipers, 20 means for supporting and positioning a shoe on a last with one end of its sole and upper in co-operative relation to the wipers and with the end of the last, upper and sole spaced from the inner edges of the open 25 wipers, and power operated mechanism organized to updraw and outdraw the upper materials at said end of the last against the wipers to stretch and smooth out the upper materials preparatory to the closing of the 30 wipers, and subsequently to close the wipers over the edge of the shoe sole without pressing the upper against the side of the last.

7. A machine of the class described having, in combination, end embracing wipers, 35 means for supporting and positioning a shoe on a last with one end of its sole and upper in co-operative relation to the wipers and with the end of the last, upper and sole spaced from the inner edges of the open 40 wipers, and power operated mechanism organized to updraw and outdraw the upper materials at said end of the last to stretch and smooth out the upper materials preparatory to the closing of the wipers, and subsequently to close the wipers over the edge 45 of the sole without pressing the upper against the side of the last above the sole, the upper stretching means being effective to maintain the outward stretching tension on 50 the upper materials while the wipers are closing to and advancing over the edge of the sole.

8. A toe lasting machine having, in combination, toe embracing wipers mounted for 55 relative closing movement approximately in the plane of the sole at the toe end of a supported last, means to support and position a shoe on a last with the toe end of the sole spaced from the inner edges of the open 60 wipers, power operated mechanism organized to pull and stretch the upper materials at the toe end of the last upwardly, laterally and forwardly, to maintain the wipers in substantially open position during such up- 65 draw, lateral outdraw and foredraw of the

upper and subsequently to advance and close the wipers over the edge of the sole without pressing the upper against the side of the toe of the last.

9. A toe lasting machine having, in combination, toe embracing wipers mounted for closing movement in a single plane, means to position and support a last, sole and shoe upper with the toe end of the last spaced from the inner edges of the open wipers, and power operated mechanism organized to grip laterally outdraw and foredraw the toe end of the upper to stretch the upper preparatory to the closing of the wipers, and subsequently to close the wipers over the 80 edge of the sole without pressing the upper against the side of the toe of the last.

10. A toe lasting machine having, in combination, toe embracing wipers mounted for closing movement in a single plane, means 85 to position and support a last, sole and shoe upper with the toe end of the last spaced from the inner edges of the open wipers, and power operated mechanism organized to outdraw laterally and to foredraw the toe 90 end of the upper to stretch the upper preparatory to the closing of the wipers, and subsequently to close the wipers over the edge of the sole without pressing the upper 95 against the side, the upper stretching means being operative to maintain tensioning outdraw on the upper as the wipers close to and advance over the edge of the sole.

11. A machine of the class described having, in combination, end wipers mounted for closing movement in a single plane, means to support a last with its sole and shoe upper in lasting position, means to pull and stretch the supported upper outwardly from the last against and over the inner edges of the open wipers, and wiper controlling mechanism operative to maintain the wipers in substantially open position during such outward stretching action and subsequently to close the wipers approximately in the 100 plane and over the bottom of a sole on the last.

12. A machine of the class described having, in combination, end wipers mounted for closing movement in a single plane, means to support a last with its sole and shoe upper in lasting position, means to pull and stretch the supported upper outwardly from the last against and over the inner edges of the open wipers, and wiper controlling mechanism operative to maintain the wipers in substantially open position during such outward stretching action and subsequently to close the wipers approximately in the plane of and over the bottom 105 of a sole on the last, the upper pulling means being arranged to maintain outward stretching tension on the upper as the wipers close to and advance over the edge 110 of the sole on the last bottom.

13. A machine of the class described having, in combination, end wipers mounted for closing movement in a single plane, means to grip the edge of the upper at the 5 end of the last to be operated upon by the wipers, means to support a last with its sole and shoe upper in lasting position, means to operate said gripping means to grip the edge of the upper and to outdraw and 10 stretch the upper against and over the inner edges of the open wipers, and wiper controlling mechanism operative to maintain the wipers in substantially open position during such outdrawing and stretching 15 action and subsequently to close the wipers over the bottom of the sole on the last bottom.

14. A machine of the class described having, in combination, end wipers mounted 20 for closing movement in a single plane, gripping means positioned above the wipers for engaging the upstanding edge of a shoe upper, means to support a last with its sole and shoe upper in co-operative relation to 25 the gripping means, means to operate said gripping means to grip the edge of the positioned upper, means to cause relative movement of said supporting and gripping means to stretch the upper against and over the 30 inner edges of the open wipers and to position the last with its sole approximately in the plane of said wipers, and means operative to maintain the wipers in substantially open position during such relative movement 35 and subsequently to close the wipers over the edge of the sole on the last.

15. A machine of the class described having, in combination, end wipers mounted for closing movement in a single plane, gripping means positioned above the wipers for 40 engaging the upstanding edge of a shoe upper, means to support a last with its sole and shoe upper in co-operative relation to the gripping means, means to operate said 45 gripping means to grip the edge of the positioned upper, means to cause relative movement of said supporting and gripping means to updraw, outdraw and stretch the upper against and over the inner edges of the open 50 wipers and to position the last with its sole approximately in the plane of said wipers, and means operative to maintain the wipers in substantially open position during such relative movement and subsequently to close 55 the wipers over the edge of the sole on the last.

16. A machine of the class described having, in combination, end wipers mounted for closing movement in a single plane, means to 60 support and position a last with its sole and shoe upper spaced from the inner edges of the open wipers, means to pull and stretch the supported upper outwardly from the last against and over the inner edges of 65 the open wipers, mechanism operative to

maintain the wipers in substantially open position during such outward stretching action and subsequently to close the wipers approximately in the plane of and over the bottom of a sole on the last. 70

17. A machine of the class described having, in combination, end wipers mounted for closing movement in a single plane, gripping means positioned in a plane removed from the plane of the wipers for engaging 75 the edge of a shoe upper, means to support a last with its sole and shoe upper in co-operative relation to the gripping means and with the end of the last and the upper spaced vertical from the inner edges of the 80 open wipers, means to operate said gripping means to grip the edge of the positioned upper, means to cause relative movement of said supporting and gripping means to updraw, outdraw and stretch the upper against 85 and over the inner edges of the open wipers and to position the last with its sole approximately in the plane of said wipers, and means operative to maintain the wipers in substantially open position during such relative movement and subsequently operable to 90 close the wipers over the edge of the sole on the last.

18. A machine of the class described having, in combination, end wipers mounted for 95 closing movement in a single plane, gripping means positioned in a plane removed from the plane of the wipers for engaging the upstanding edge of a shoe upper, means to support a last with its sole and shoe 100 upper in co-operative relation to the gripping means and with the end of the last and the upper spaced from the inner edges of the open wipers, means to operate said gripping means to grip the edge of the positioned upper, means to cause relative movement of said supporting and gripping means to updraw, outdraw and stretch the upper 105 against and over the inner edges of the open wipers and to position the last with its sole approximately in the plane of said wipers, and means operative to maintain the wipers in substantially open position during such relative movement and subsequently operable to close the wipers over the edge of the 110 sole on the last, with means to maintain said stretching tension on the upper as the wipers close to and advance over the edge of the sole on the last.

19. A machine of the class described having, 115 in combination, end wipers, means to support a last and shoe upper with the end of the last and shoe to be operated upon by said wipers spaced from the inner edges of the open wipers, means for stretching the edge 120 of the upper outwardly against and over the edge of the open wipers, and wiper controlling mechanism operative to maintain the wipers in substantially open position 125 during such stretching action and operative 130

to close said wipers approximately in the plane of the shoe sole to draw the stretched upper against and conform it to the end of the supported last and to fold it in over the 5 edge of the sole.

20. A machine of the class described having, in combination, end wipers, means to support a last and shoe upper with one end spaced from the inner edges of said wipers 10 and with the sole on the last bottom removed from the plane of closing movement of said wipers, means for relatively moving the wipers and the last and shoe approximately to aline said sole with the plane of the 15 wipers, means coincidentally operative to stretch the edge of the upper forwardly and outwardly against and over the inner edges of the open wipers, and means constructed and arranged to permit the wipers to remain 20 in substantially open position during said stretching action and operable to close the wipers approximately in the plane of the shoe sole to draw the stretched upper against and conform it to the end of the supported 25 last end and to fold it in over the edge of said shoe sole.

21. A machine of the class described having, in combination, end wipers mounted for closing movement in a single plane, 30 means to support and position a last and shoe upper with its inner end spaced from the inner edges of said wipers and with the sole on the last bottom in a plane removed from the plane of said wipers, means for 35 gripping the edge of the upper at said end of the last, means for bodily moving the last and shoe approximately to aline said shoe sole with the wipers and to cause said gripping means to updraw the upper, means 40 coincidentally operable to cause said gripping means to outdraw laterally and to fore-draw said upper, and wiper controlling mechanism arranged to permit said wipers to remain substantially open during said 45 updraw, foredraw and outdraw on the upper and operable to close the wipers approximately in the plane of the sole to draw the stretched upper against and conform it to the end of the last and to fold it in over the 50 edge of the shoe sole.

22. A machine of the class described having, in combination, end wipers mounted for closing movement in a single plane, means to support and position a last and shoe upper 55 per with its inner end spaced from the inner edges of said wipers and with the sole on the last bottom in a plane removed from the plane of said wipers, means for gripping the edge of the upper at said end of the last, 60 means for bodily moving the last and shoe approximately to aline said shoe sole with the wipers and to cause said gripping means to updraw the upper, means coincidentally operable to cause said gripping means to

outdraw laterally and to foredraw said upper, and wiper controlling mechanism arranged to permit said wipers to remain substantially open during said updraw, foredraw and outdraw on the upper and operable in timed relation to close the wipers approximately in the plane of the sole to draw the stretched upper against and conform it to the end of the last and to fold it in over the edge of the shoe sole, with means to maintain outward tension on the upper as 75 the wipers close and advance over the edge of the sole on the last.

23. A machine of the class described having, in combination, end wipers mounted for closing movement in a single plane, grippers positioned in a plane removed from the plane of the wipers, means to support and position a last with its shoe upper in co-operative relation to the grippers and spaced from the edge of the open wipers with the 80 sole on the last in a plane removed from the plane of the wipers, power operated means to close the grippers on the upper and subsequently relatively to move the last supporting means and wipers to position the 85 sole approximately in the plane of the wipers and coincidentally to move the grippers to outdraw and stretch the edge of the upper forwardly over the open wipers, and wiper controlling means effective to 90 maintain the wipers in substantially open position during such outdrawing and stretching movement and subsequently operable in timed relation to close the wipers over the edge of the sole to draw the 95 stretched upper against the end of the last and to fold it in over the edge of the sole.

24. A machine of the class described having, in combination, end wipers mounted for closing movement in a single plane, grippers positioned in a plane removed from the plane of the wipers, means to support and position a last with its shoe upper in co-operative relation to the grippers and spaced from the edge of the open wipers with the 100 sole on the last in a plane removed from the plane of the wipers, power operated means to close the grippers on the upper and subsequently relatively to move the last supporting means and wipers to position the 105 sole approximately in the plane of the wipers and coincidentally to move the grippers to outdraw and stretch the edge of the upper forwardly over the open wipers, and wiper controlling means effective to maintain the 110 wipers in substantially open position during such outdrawing and stretching movement and subsequently operable in timed relation to close the wipers over the edge of the sole to draw the stretched upper against 115 the end of the last and to fold it in over the edge of the sole, said gripper moving means operating in timed relation to the 120 125

closing of the wipers to maintain outward tension on the upper as the wipers close to and advance over the edge of the sole.

25. A machine of the class described having, in combination, end embracing wipers mounted for closing movement in a single plane, gripping means positioned in a plane removed from the plane of the wipers for engagement with the edge of a shoe upper, last and shoe supporting means movable to position and hold a last and its shoe upper in co-operative relation to said gripping means with the sole on the last in a plane removed from the plane of the wipers, power operated mechanism operative to so position the last, sole and shoe upper and to close the grippers and subsequently to move the last to updraw the upper and to position the sole approximately in the plane of the wipers, said grippers being coincidentally operative by said power means to outdraw and stretch the gripped upper forwardly over the open wipers, and wiper controlling means constructed and arranged to permit the wipers 25 to remain substantially open during said updraw and outdraw on the upper and subsequently operable to close the wipers over the edge of the sole to draw the stretched upper against the end of the last and to fold it in over the edge of the sole.

26. A machine of the class described having, in combination, end embracing wipers mounted for closing movement in a single plane, a gage for positioning a last and shoe upper with the upper at the end of the last spaced from the inner edges of the open wipers, means to support a last and shoe with the sole on the last in co-operative relation to said gage and in a plane removed 40 from the plane of the wipers, pincers for gripping the edge of the upper at the end of the last having lower fixed jaws positioned below said gage and above the plane of the wipers, means to operate said pincers 45 to grip the upper, means relatively to move said supporting means and pincers to position the sole approximately in the plane of the wipers and to updraw and outdraw forwardly the edge of the upper against 50 and over the inner edges of the open wipers, and wiper operating means constructed and arranged to permit the wipers to remain substantially open during updraw and outdraw of the upper and operative subsequently to close the wipers over the edge 55 of the sole to draw the stretched upper against the end of the last and to fold it in over the edge of the sole.

27. A machine of the class described having, in combination, end wipers mounted for closing movement in a single plane, a gage arranged determinately to engage the sole lip to position a shoe upper and a last with the upper on the end of the last spaced from 60 the inner edges of the open wipers and with

the sole in a plane removed from the plane of said wipers, means to clamp and support a last, sole and upper with the sole determinately in engagement with said gage, means to grip the edge of the shoe upper 70 at a point removed from the plane of the wipers, power operated means to operate said gripping means and to move the last support to position its sole approximately in the plane of the wipers and coincidentally 75 to effect updraw and outdraw on the upper to stretch said upper outwardly over the inner edge of the open wipers, and power operated wiper controlling means effective to maintain said wipers in substantially 80 open position during said updraw and outdraw on the upper and operable subsequently in timed relation to close the wipers over the edge of the sole to draw the stretched upper against the end of the last and to fold 85 it in over the edge of the sole.

28. A toe lasting machine having, in combination, toe embracing wipers mounted for closing movement in a single plane, means to position and support a last, sole and shoe 90 upper with the toe end of the last spaced from the inner edges of the open wipers, and mechanism organized to outdraw and stretch the toe end of the upper against and over the inner edges of the open wipers 95 preparatory to the closing of the wipers, to maintain the wipers open during such outdraw and subsequently to close the wipers over the edge of the sole to draw the stretched upper against the toe of the last 100 and to fold it in over the edge of the sole.

29. A toe lasting machine having, in combination, end wipers mounted for closing movement in a substantially horizontal plane, means to position and support a last, sole and shoe upper with the toe end of the last spaced from the inner edges of the open wipers, means to outdraw the toe end of the upper forwardly against and over the inner 105 edges of the open wipers to stretch the upper preparatory to the closing of the wipers, and means for subsequently closing the wipers over the edge of the sole to draw the stretched upper against the toe of the last 110 and to fold it down over the edge of the sole, said upper stretching means being constructed and operative to maintain tensioning outdraw on the upper as the wipers close to and advance over the edge of the sole.

30. A toe lasting machine having, in combination, end wipers mounted for closing movement in a single plane, means to position and support a last, sole and shoe upper with the toe end of the last spaced from the inner edges of the open wipers and with the sole on the last in a plane removed from the plane of the wipers, means to grip the edge of the shoe upper at the toe of the last, means bodily to move the last support and 125 130

- last in a direction to position the sole approximately in the plane of and spaced from the edges of the wipers and to updraw the gripped upper, means coincidently operable to move the gripping means to outdraw and stretch the upper forwardly over the edges of the open wipers, and wiper controlling and operating mechanism effective to maintain the wipers in substantially open 50
- 10 position during such updraw and outdraw and operable subsequently to close the wipers over the edge of the sole to draw the stretched upper against the toe of the last and to fold it in over the edge of the sole. 70
- 15 31. A toe lasting machine having, in combination, toe embracing wipers, means for supporting and positioning a last with its sole and upper in co-operative relation to the wipers, upper stretching means arranged 80
- 20 for operation to updraw and outdraw the upper against the inner edges of the open wipers to stretch the upper preparatory to the closing of the wipers, and wiper controlling mechanism operated in timed relation 85
- 25 to said upper stretching means and organized to hold the wipers open during said upper stretching movement and subsequently to close the wipers over the edge of the sole without a preliminary pressure 90
- 30 of the wipers against the last above the plane of the sole. 95
32. A toe lasting machine having, in combination, toe embracing wipers mounted for closing movement in a single plane, grippers located in a plane removed from the plane 100
- 35 of the wipers to engage the edge of the upper at the toe, means for supporting a last with the toe portion of its shoe upper in co-operative relation to the grippers and 105
- 40 with the sole on the last bottom in a plane removed from the plane of the wipers and the toe end of the last spaced from their inner edges, means for moving the last support to position the shoe sole in approximately the same plane as the wipers and to cause the grippers to updraw the gripped upper, means for moving the grippers to stretch the toe end of the upper outwardly against and over the edge of the open wipers, 110
- 45 and wiper controlling mechanism operated in timed relation to said gripper movement to hold the wipers open during said outward stretching movement and subsequently to close the wipers over the edge of the sole. 115
- 50 33. A toe lasting machine having, in combination, toe embracing wipers, means for supporting and positioning a last with its sole and upper in co-operative relation to the wipers, upper stretching means arranged for 120
- 55 operation to updraw and outdraw the upper against the inner edges of the open wipers to stretch the upper preparatory to the closing of the wipers, and wiper controlling mechanism operated in timed relation to said upper stretching 125
- 60 means and organized to hold the wipers in open position during said outdrawing and stretching movement and subsequently to close the wipers over the margin of the sole without preliminary movement of the wipers perpendicularly to the plane of the sole. 130

37. A machine for lasting the toes of turn shoes having, in combination, toe embracing wipers, means to support a last with its sole and shoe upper in lasting position, means to stretch the upper at the toe outwardly and forwardly over the wipers, and wiper controlling and operating mechanism operated in timed relation to said upper stretching means and organized to hold the wipers in open position during said upper stretching movement and subsequently to close the wipers over the edge of the sole in a plane approximately coincident with the plane of the sole on the last bottom without preliminary movement of the wipers perpendicularly to the plane of the sole, said upper stretching means being constructed and arranged to maintain stretching tension on the upper as the wipers close to and advance over the edge of the sole.

38. A machine for lasting the toes of turn shoes having, in combination, toe embracing wipers, means to support a last with its sole and shoe upper in lasting position with the end of the last toe spaced from the inner edges of the open wipers, means to stretch the toe portion of the upper outwardly and forwardly against and over the edges of the open wipers, and wiper controlling and operating mechanism operated in timed relation to the upper stretching means and organized to maintain the wipers in open position during such stretching action and subsequently to close the wipers over the edge of the sole without preliminary pressure of the wipers against the side of the toe of the last, said upper stretching means being constructed and arranged to maintain stretching tension on the upper as the wipers close to and advance over the edge of the sole.

39. In a toe lasting machine, in combination, end wipers arranged to close over the sole at the toe end of a last, means to support a last with its sole and shoe upper in co-operative relation to the wipers, grippers arranged to engage the edge of the upper at the corners of the toe, means to swing said grippers outwardly and forwardly about axes located rearwardly of the grippers to withdraw laterally and to foredraw the upper at the corners of the toe, and means to operate the wipers.

40. In a toe lasting machine, end wipers arranged to close over the sole at the toe end of a last, means to support a last with its sole and shoe upper in co-operative relation to the wipers, grippers positioned to engage the edge of the upper at the corners of the toe, an end gripper positioned at the extreme forward end of the toe, means to move said end gripper forward to withdraw and foredraw the gripped toe end of the upper and coincidently to swing said corner grippers outwardly and forwardly about axes located rearwardly of the gri-

pers in the direction of the heel of the last to withdraw laterally and to foredraw the upper at the corners of the toe, and means to close the wipers.

41. In a lasting machine, in combination, end wipers arranged to close over the sole at the toe end of a last, means to support a last with its sole and shoe upper in co-operative relation to the wipers, corner grippers mounted at the corners of the toe end of the last, means to operate said grippers to grip the edge of the upper at the corners of its toe portion, and means subsequently operative to swing said grippers to withdraw in a diagonally forward direction with a substantially decreased outward component of movement at the ends of the grippers adjacent to the tip seam of the toe.

42. In a toe lasting machine, in combination, end wipers arranged to close over the sole at the toe end of a last, means to support a last with its sole and shoe upper in co-operative relation to the wipers, grippers positioned to engage the edge of the upper at the corners of the toe, and means to swing said grippers laterally outward from the sides of the toe in curved paths about axes so disposed as to secure a diagonally forward withdraw on the upper at the corners of the toe with the upper rearwardly of the corners tensioned substantially in a forward direction only.

43. In a toe lasting machine, in combination, end wipers arranged to close over the sole at the toe end of a last, means to support a last with its sole and shoe upper in co-operative relation to the wipers, grippers positioned to engage the edge of the upper at the corners of the toe, means to swing said grippers outwardly and forwardly about axes located outwardly and rearwardly of the grippers, and means to operate the wipers.

44. In a machine of the class described, in combination, end wipers, means to support a last with its sole and shoe upper in operative relation to said wipers, grippers arranged to grip the edge of the upper at opposite sides of and closely adjacent to one end of the last, means for bodily adjusting the grippers toward and from each other transversely of the last, and independent means for angularly adjusting the grippers about axes substantially perpendicular to the bottom of the last.

45. In a machine of the class described, in combination, end wipers, means to support a last with its sole and shoe upper in operative relation to said wipers, grippers positioned to grip the edge of the upper at opposite sides of one end of the last, means for bodily and independently adjusting the grippers toward and from each other transversely of the last, and inde-

pendent means for angularly and independently adjusting the grippers about axes substantially perpendicular to the bottom of the last.

5 46. In a machine of the class described, in combination, end wipers, means to support a last with its sole and shoe upper in operative relation to said wipers, grippers arranged to grip the edge of the upper 70
10 at opposite sides of one end of the last, means for bodily adjusting the grippers toward and from each other transversely of the last, independent means for angularly adjusting the grippers about axes substantially 75
15 perpendicular to the bottom of the last, and means for swinging the adjusted grippers bodily outwardly from the opposite sides of the last in a diagonally forward direction to outdraw the gripped
20 upper forwardly toward the end of the last.

47. In a machine of the class described, in combination, end wipers, means to support a last with its sole and shoe upper in co-operative relation to said wipers, pivoted gripper supports at opposite sides of the last, means for bodily adjusting said supports toward and from each other transversely of the last, grippers depending from said supports and arranged to grip 80
25 the edge of the upper at opposite sides of said end of the last, and means for angularly adjusting said grippers relatively to their supports about axes substantially perpendicular to the bottom of the last.

25 48. In a machine of the class described, in combination, end wipers, means to support a last with its sole and upper in co-operative relation to said wipers, grippers arranged to grip the edge of the upper at opposite 85
30 sides of the end of the last, and means for bodily and independently adjusting said grippers toward and from each other transversely of the last, and for angularly and independently adjusting said grippers about 90
35 axes substantially in alinement with their active gripping portions.

49. In a machine of the class described, in combination, end wipers, means to support a last with its sole and upper in co-operative relation to said wipers, grippers arranged to grip the edge of the upper at opposite sides of the end of the last, means for bodily and independently adjusting said grippers toward and from each 95
40 other transversely of the last, and for angularly and independently adjusting said grippers about axes substantially in alinement with their active gripping portions, and means for swinging the adjusted 100
45 grippers outwardly in a diagonally forward direction to outdraw the gripped upper forwardly toward the end of the shoe.

50. In a machine of the class described, in combination, end wipers, means to support 105
50 a last with its sole and upper in co-operative

relation to said wipers, gripper supports at opposite sides of the last mounted for bodily adjustment toward and from each other transversely of the last, and grippers for engaging opposite sides of the shoe upper 70
75 at one end of the last mounted on said supports for angular adjustment relatively to their supports about axes substantially in alinement with their active gripping portions.

51. In a machine of the class described, in combination, end wipers, means to support a last with its sole and shoe upper in co-operative relation to the wipers, grippers supported above said wipers and arranged 80
80 to grip the edge of the upper at opposite sides of the end of the last, means for bodily and independently adjusting said grippers toward and from each other transversely of the last, and independent means for angularly and independently adjusting said grippers about axes located approximately in alinement with the ends of the grippers adjacent to said end of the last.

52. In a machine of the class described, in combination, end wipers, means to support a last with its sole and shoe upper in co-operative relation to said wipers, grippers supported at one end and at opposite sides of said end of the last and arranged to grip 95
95 the edges of the shoe upper at said sides and end, means for bodily adjusting the side grippers toward and from each other transversely of the last and relatively to the end gripper, independent means for adjusting 100
100 the side grippers angularly relatively to said end gripper and about axes substantially perpendicular to the last bottom, and means for simultaneously moving the side and end grippers outwardly from the last.

53. In a toe lasting machine, in combination, end wipers, means to support a last with its sole and shoe upper in co-operative relation to said wipers, grippers supported at the extremity of the toe end and at opposite corners of said toe end of the last and arranged to grip the edges of the shoe upper at said corners and extremity of the toe, means for bodily and independently adjusting the corner grippers toward and from 110
115 each other transversely of the last and relatively to the end gripper, independent means for angularly and independently adjusting the corner grippers relatively to the end gripper and about axes substantially perpendicular to the last bottom, and means for simultaneously moving said grippers outwardly from the last.

54. In a toe lasting machine, in combination, end wipers, means to support a last with its sole and shoe upper in co-operative relation to said wipers, grippers supported at the extremity of the toe end and at opposite corners of said toe end of the last and arranged to grip the edges of the shoe upper 120
125
130

at said corners and extremity of the toe, means for bodily and independently adjusting the corner grippers toward and from each other transversely of the last and relatively to the end gripper, independent means for angularly and independently adjusting the corner grippers relatively to the end gripper and about axes substantially perpendicular to the last bottom and in substantial alinement with the forward ends of the corner grippers, and means for simultaneously moving said grippers outwardly from and forwardly of the last.

55. In a machine of the class described, in combination, end wipers, means to support a last with its sole and shoe upper in co-operative relation to said wipers, grippers supported at one end and at opposite sides of said end of the last and arranged to grip the edges of the shoe upper at said sides and end, means for bodily adjusting the side grippers toward and from each other transversely of the last and relatively to the end gripper, independent means for adjusting the side grippers angularly relatively to said end gripper and about axes substantially perpendicular to the last bottom, and operating connections to said end and side grippers effective to move said end gripper forwardly from the last and simultaneously to swing said side grippers outwardly in diagonally forward directions.

56. In a machine of the class described, in combination, end wipers, means to support a last with its sole and shoe upper in co-operative relation to the wipers, opposed gripper supports independently adjustable toward and from each other transversely of the last, grippers carried by said supports at points above the wipers arranged to grip the edge of the upper at opposite sides of the end of the last, means independently to adjust said grippers relatively to their supports and about axes substantially perpendicular to the plane of the last bottom, means to close said grippers on the edge of the upper, and means bodily to move said grippers laterally outward from the opposite sides of the last.

57. In a machine of the class described, in combination, end wipers, means to support a last with its sole and shoe upper in co-operative relation to the wipers, pivot members at opposite sides of the last mounted for independent adjustment toward and from each other transversely of the last, gripper supports pivotally carried by said members and mounted for transverse adjusting movement therewith, grippers carried by and depending from said supports arranged to grip the edge of the upper at opposite sides of the end of the last, means independently to adjust said grippers on their supports about axes substantially perpendicular to the plane of the last bottom and in substantial alinement with their gripping faces, means to close said grippers on the edge of the upper, and means to move the grippers laterally outward from the opposite sides of the last.

58. In a machine of the class described, in combination, end wipers, means to support a last with its sole and shoe upper in co-operative relation to the wipers, pivot members at opposite sides of the last adjacent to one end mounted for independent adjustment toward and from each other transversely of the last, side gripper supports pivotally carried by said members and mounted for transverse adjusting movement therewith, side grippers carried by and depending from said supports and arranged to grip the edge of the upper at opposite sides of the end of the last, means independently to adjust said grippers on their supports about axes substantially perpendicular to the last bottom, an end gripper support, a gripper carried by and depending from said support and arranged to grip the edge of the upper at the extreme end of the last, means simultaneously to close the side and end grippers upon the edge of the upper, and operating means including connections between the end gripper and side gripper supports, constructed and arranged bodily to move the end gripper laterally forward away from the end of the last and coincidently to swing the side gripper supports and the side grippers laterally outwardly and forwardly from the opposite sides of the last about the pivots of said side gripper supports to foredraw and outdraw the upper.

59. In a machine of the class described, in combination, end wipers, means to support a last with its sole and shoe upper in co-operative relation to the wipers, a normally stationary end gripper support, a gripper carried by and depending from said end support and arranged to grip the edge of the upper at the extreme end of the last, blocks at opposite sides of the last adjacent to one end mounted for independent straight line adjusting movement toward and from each other transversely of the last and relatively to said end gripper and its support, side gripper supports pivotally carried by said blocks and mounted for transverse adjusting movement therewith, side grippers carried by and depending from said supports and arranged to grip the edge of the upper at opposite sides of said extreme end of the last, means independently to adjust said side grippers on their supports and relatively to the stationary end gripper about axes substantially perpendicular to the plane of the last bottom and substantially alined with the forward ends of the side grippers, means simultaneously to close the side and end grippers upon the edge of the upper, and operating mechanism for the grippers, including connections between the end and

side gripper supports, effective bodily to move the end gripper laterally forward and coincidently to swing the side grippers and their supports laterally and forwardly outward about the pivots of said side gripper supports.

60. In a toe lasting machine, in combination, end wipers, means to support a last with the toe end of its sole and shoe upper 10 in co-operative relation to the wipers, a normally stationary end gripper support, a gripper carried by and depending from said end support and arranged to grip the edge of the upper at the extreme end of the toe 15 of the last, blocks at opposite sides of the last adjacent to its toe end mounted for independent straight line adjusting movement toward and from each other transversely of the last and relatively to said toe 20 end gripper and its support, corner gripper supports pivotally carried by said blocks and mounted for transverse adjusting movement therewith, corner grippers carried by and depending from said supports and arranged to grip the edge of the upper at the opposite corners of said toe end of the last, means independently to adjust said corner grippers on their supports and relatively to the stationary end gripper about axes sub- 25 stantially perpendicular to the plane of the last bottom and substantially alined with the forward ends of the corner grippers, means simultaneously to close the corner and end grippers upon the edge of the upper, and operating mechanism for the grippers, including connections between the end and corner gripper supports, effective bodily to move the end gripper laterally forward and coincidently to swing the corner grippers and their supports laterally and forwardly outward about the pivots of said corner gripper supports.

61. In a machine of the class described, the combination of end wipers, means to support 45 a last with one end of its sole and shoe upper in co-operative relation to the wipers, grippers having straight gripping jaws supported and positioned at the extreme end and at opposite sides of and adjacent to said 50 end of the last, means bodily to adjust the side grippers from and toward each other and relatively to the end gripper transversely of the last, and means angularly to adjust the side grippers relatively to the 55 end gripper about axes substantially perpendicular to the last bottom and substantially alined with their respective gripping jaws.

62. In a machine of the class described, 60 the combination of end wipers, means to support a last with one end of its sole and shoe upper in co-operative relation to the wipers, grippers having straight gripping jaws supported and positioned at the ex- 65 treme end and at opposite sides of and ad-

jacent to said end of the last, means independently and bodily to adjust the side grippers from and toward each other and relatively to the end gripper transversely of the last, and means independently and angularly to adjust the side grippers relatively to the end gripper about axes substantially perpendicular to the last bottom and substantially alined with the ends of their respective gripping jaws adjacent to said end 70 gripper.

63. In a toe lasting machine, toe wipers, means to support a last with the toe end of its sole and shoe upper in co-operative relation to the wipers, grippers having straight gripping jaws supported and positioned at the extreme end of the toe and at the opposite corners of the toe of the last, means bodily and independently to adjust the corner grippers toward and from each other transversely of the toe of the last for variance in the width of the toe, and independent means for independently swinging the corner grippers about axes substantially perpendicular to the plane of the last bottom and substantially alined with the forward ends of their respective gripping jaws to accommodate the corner grippers to variance in curvature of the toe ends of lasts.

64. In a machine of the class described, in combination, end wipers, a positioning gage above the wipers against which the sole on a last is held, means to support a last with its sole engaged and determinately positioned by said gage, and means for gripping the edge of the shoe upper at the end of the last including grippers having upper and lower gripping jaws, the lower jaws of said grippers being fixed and positioned substantially above the inner edges of the open wipers and below said gage to receive the edge of the upper when the last and sole are determinately positioned relatively to said gage.

65. In a machine of the class described, in combination, end wipers supported against movement substantially perpendicularly to the plane of the bottom of the supported shoe, a positioning gage normally removed from the plane of said wipers in the direction of the height of a supported last and shoe and against which the sole on a last is held, means to support a last, sole and shoe upper with the sole positioned by said gage in a plane removed from the plane of the wipers and grippers normally positioned to engage and hold the edge of the shoe upper at the end of the last, said grippers having fixed jaws positioned in a plane between said gage and wipers and substantially alined with the inner edges of the wipers in their open position.

66. In a machine of the class described, in combination, end wipers, a positioning gage

normally removed from the plane of the wipers in the direction of the height of a supported last and shoe and against which the sole is manually held, treadle controlled means to clamp a last with its sole and upper in the position determined by said gage, pincers for gripping the upstanding edge of the shoe upper at the end of the last having fixed jaws positioned in a plane between said 5 gage and wipers and substantially aligned with the inner edges of the open wipers and having gripping faces extending obliquely outwardly in the direction of the height of the last to receive and guide the edge of the 10 upper between the pincer jaws when the sole is presented to the gage.

67. In a machine of the class described, in combination, end wipers, a positioning gage normally removed from the plane of the 20 wipers in the direction of the height of the last and shoe and against which the sole on a last is manually held, pincers for gripping the edges of the upper at the end of the last having jaws positioned in a plane between 25 said gage and wipers and substantially aligned with the inner edges of the open wipers, and treadle controlled power operated means to move said gage determinately in the direction of last height and to clamp the last with 30 its sole and upper in the position determined by said gage and coincidently to operate said pincers to grip the upper.

68. In a machine of the class described, in combination, end wipers supported against 35 movement perpendicularly to the plane of the sole of a supported shoe, a positioning gage normally removed from the plane of the wipers in the direction of the height of the last and against which the sole on a last 40 is manually held, pincers for gripping the upstanding edges of the upper at the end of the last having fixed jaws positioned between said gage and wipers and substantially above the inner edges of the open wipers, and 45 treadle controlled power operated means to move said gage a determinate distance in the direction of height of the last and to clamp the last with its sole and upper in the position determined by said gage and coincidently to operate said pincers to grip the upper, said power operated means being operable further in timed relation determinately to move the last and upper to updraw the upper and to position the shoe sole approximately in the plane of the wipers, coincidently to move the pincers laterally away from the last to outdraw the upper and subsequently to close the wipers over the edge of the sole.

60 69. In a machine of the class described, in combination, end wipers, a positioning gage normally removed from the plane of the wipers in the direction of the height of a supported last and shoe and against which the sole on a last is held, means to support a

last, sole and shoe upper with the sole determinately positioned by said gage in a plane removed from the plane of the wipers in the direction of the height of the last, and pincers for gripping the edge of the upper 70 at the end of the last having fixed jaws positioned in a plane between the gage and wipers and substantially aligned with the inner edge of the open wipers to position the ends of said fixed jaws below the plane of the 75 sole on the positioned last.

70. In a toe lasting machine, in combination, end wipers, a positioning gage above the wipers against which the lip on the shoe sole at the extremity of the toe is held, means 80 to support a last, sole, and shoe upper with the sole lip co-operating with said gage determinately to locate the shoe relatively to the wipers, and means for gripping the edge of the shoe upper at the toe end of the last 85 including grippers having lower jaws maintained at a determinate distance below the gage substantially above the inner edges of the open wipers and extending laterally outwardly and upwardly from the side of the 90 last.

71. In a toe lasting machine, in combination, toe wipers, a holddown member and an opposed toe supporting member relatively movable toward each other to clamp the last, 95 sole, and upper between them, a positioning gage adjacent to the holddown normally removed from the plane of the wipers in the direction of the height of the last and shoe and against which is held the lip of the shoe 100 sole at the extremity of the toe, treadle controlled means for determinately moving said gage and coincidently moving said holddown and toe support toward each other to clamp the last, sole and shoe upper between them 105 with the sole positioned in the plane determined by the position of said gage, and pincers located between the wipers and said gage for gripping the edge of the upper at the toe of the clamped and positioned last. 110

72. In a toe lasting machine, in combination, toe wipers, a holddown member and an opposed toe supporting member movable toward each other to clamp the last, sole and upper between them, a positioning gage removed from the plane of the wipers and adjacent to the holddown member against which is held the outer face of the lip on the shoe sole at the extremity of the toe, grippers arranged to grip the edge of the upper at 115 the toe end of the clamped and positioned last, and treadle controlled power operating mechanism constructed and arranged determinately to move the gage and coincidentally to move the last, sole and upper with the sole maintained in engagement with the gage to position the sole approximately in the plane of the wipers.

73. A machine of the class described having, in combination, end wipers, a gage 120

above the plane of the wipers against which the sole on a last is determinately positioned, grippers supported in a plane removed from the plane of the wipers and each having a 5 fixed jaw and a relatively movable jaw constructed and arranged to move to grip in a curved path having an outward component until near the end of its gripping movement and thence having a substantial inward component to gather and clamp the upper materials against the fixed jaw, means to support a last with its sole determinately positioned relatively to said gage and above the plane of the wipers, means to move said 10 gripper jaws relatively to clamp the upper, means relatively to move the last and wipers to position the sole and wipers approximately in the same plane, and means to close the wipers over the edge of the sole. 15

20 74. A machine of the class described having, in combination, end wipers, a gage against which the sole on a last is determinately positioned with the end of the last spaced from the edges of the wipers 25 and with the sole on the last above the plane of the wipers, means to support a last and shoe with its sole in such relation to said gage, grippers having fixed jaws and relatively movable jaws movable longitudinally 30 and outwardly, and thence inwardly to gather the upper material against the fixed jaws, means to depress the last support and last to cause said grippers to updraw the upper and to position the last with its sole approximately in the plane of said wipers, and means to operate the wipers to close over the edge of the sole. 35

75. A machine of the class described having, in combination, end wipers, a gage 40 above the plane of the wipers against which the sole on a last is determinately positioned, grippers above the plane of the wipers and each having a fixed jaw and a relatively movable jaw constructed and arranged, in closing, to move longitudinally in a curved path having an outward component until near the end of its closing movement and thence having a substantial inward component to gather and clamp the upper materials against the fixed jaw, means to support a last with its sole determinately positioned relatively to said gage and above the plane of the wipers, means to move said gripper jaws relatively to clamp the upper 50 materials against the fixed jaw, means to support a last with its sole determinately positioned relatively to said gage and above the plane of the wipers, means to move said gripper jaws laterally outward from the side of the last, means coincidently relatively to move the last and wipers to position the sole and wipers approximately in the same plane, and 55 means to close the wipers over the edge of the sole. 60

76. A machine of the class described having, in combination, end wipers, a gage against which the sole on a last is determinately positioned with the end of the last 65

spaced from the edges of the wipers and with the sole on the last above the plane of the wipers, means to support a last and shoe with its sole in such relation to said gage, grippers having fixed jaws and relatively 70 movable jaws movable, in closing, longitudinally and outwardly and thence inwardly to gather the upper material against the fixed jaws, means to depress the last support and last to cause said grippers to updraw the upper and to position the last with the sole approximately in the plane of said wipers, means coincidently operable bodily to move the grippers laterally outward to outdraw the upper, and means to operate 75 the wipers to close over the edge of the sole. 80

77. A machine of the class described having, in combination, end wipers, a gage for the bottom of the shoe sole, grippers positioned above the wipers arranged to grip 85 the edge of the upper at one end of a positioned last, means to support and position a last with the sole in co-operative relation to the gage and above the plane of the wipers, means to operate the grippers to 90 grip the edge of the upper at the end of the last, means to depress the last support and last approximately to aline the bottom of the shoe sole with the bottom face of the wipers and to updraw the upper, means 95 coincidently operative bodily to move said grippers laterally and forwardly outward to outdraw and foredraw the upper, and means subsequently operable to close the wipers over the edge of the sole. 100

78. A toe lasting machine having, in combination, toe wipers, a gage for the toe end of the shoe sole, means to support a last with the sole in co-operative relation to said gage and above the plane of the wipers, 105 grippers supported and positioned above the wipers and arranged to grip the edge of the upper at the toe end of the last, means to depress the last support and last to cause updraw on the gripped upper and approximately to aline the toe end of the sole with the toe wipers, means coincidently operative to move said grippers laterally and forwardly outward to outdraw and foredraw the upper, and wiper operating means arranged to maintain the wipers substantially 110 in open position during such updraw and outdraw and effective subsequently to close the wipers over the toe end of the sole. 115

79. A machine of the class described having, in combination, end wipers, means for closing said wipers, opposed members relatively movable to clamp a last with a sole and shoe upper between them, means operative to cause one of said opposed members 120 to exert against the wipers as they close over the sole pressure in a direction substantially perpendicular to the plane of the bottom of the sole, and yielding means cooperating with the other of said opposed 125 130

members to cause said other member to hold the last and sole against lengthwise displacement through the closing thrust of the wipers.

5 80. A machine of the class described having, in combination, end wipers, means for closing said wipers, opposed members relatively movable to clamp a last with a sole and shoe upper between them, means to 10 cause one of said opposed members to exert against the wipers as they close over the sole yielding pressure in a direction substantially perpendicular to the plane of the sole bottom, and means for causing the other 15 of said opposed members to exert yielding pressure against the sole and last to prevent longitudinal displacement of the sole and last by closing over thrust of the wipers.

81. A machine of the class described having, in combination, end wipers, opposed members relatively movable to clamp between them a last with a sole and shoe upper in co-operative relation to the wipers, means for closing and for retracting the 20 wipers a plurality of times, means operative during each closing movement to cause one of said opposed members to exert against the wipers upper compacting pressure in a direction substantially perpendicular to the plane of the sole bottom and coincidentally to cause the other of said opposed members to exert pressure against the last and sole effective to hold them against lengthwise displacement by the closing over 25 thrust of the wipers, and means operative during retraction of the wipers to relieve such compacting pressure against the wipers to prevent drag on the upper materials.

82. A machine of the class described having, in combination, end wipers, opposed members relatively movable to clamp between them a last with a sole and shoe upper in co-operative relation to the wipers, means for closing and retracting the wipers a plurality of times, means operative during each 40 closing movement of the wipers to cause one of said opposed members to exert against the wipers yielding upper compacting pressure in a direction substantially perpendicular to the plane of the sole bottom and coincidentally to cause the other of said opposed members to exert relatively weaker pressure against the last and sole to prevent lengthwise displacement of the last and sole by 45 closing over thrust of the wipers, and means operative during retraction of the wipers to relieve compacting pressure against the wipers to prevent drag on the upper materials.

50 83. A machine of the class described having, in combination, end wipers, means to close said wipers over one end of the sole on a last, opposed members relatively movable to clamp between them a last with a

sole and shoe upper in co-operative relation 65 to the wipers, one of said opposed members being constructed and arranged to exert against the last yielding spring clamping pressure and the other of said opposed members having a relatively weaker spring providing an initial limited yielding movement, and a subsequent rigid clamping pressure against the opposite side of the last, means to cause the first mentioned of said opposed members to exert against the wipers 70 as they close over the sole yielding upper compacting pressure in a direction substantially perpendicular to the plane of the sole bottom, and means coincidentally to operate the other of said opposed members to change 75 its rigid clamping pressure against the last and sole to a yielding spring pressure relatively weaker than the compacting pressure of the first mentioned of said opposed members and effective to hold the last and 80 sole against lengthwise displacement by the closing over thrust of the wipers.

84. A toe lasting machine having, in combination, end wipers, a toe support member and an opposed sole pressing member relatively movable to clamp between them a last with a sole and shoe upper in co-operative relation to the wipers, one of said opposed members being constructed and arranged yieldingly to exert clamping pressure against the last and the other of said opposed members being constructed and arranged to exert rigid clamping pressure against the last, means to close the wipers over the sole at the toe end of the last, means to cause one of said opposed members to exert against the wipers as they close over the sole upper compacting pressure in a direction substantially perpendicular to the plane of the sole bottom, and means coincidentally to cause the other of said opposed members to exert yielding pressure against the last and sole to hold them against lengthwise displacement by the closing-over 90 thrust of the wipers.

85. A toe lasting machine having, in combination, end wipers, a toe support and an opposed sole pressing member relatively movable to clamp between them a last with a sole and shoe upper in co-operative relation to the wipers, said toe support being constructed and arranged yieldingly to exert clamping pressure against the last and said sole pressing member being constructed and arranged to exert rigid clamping pressure 95 against the sole, means to close the wipers over the sole at the toe end of the last, means to cause the toe support to exert against the wipers as they close over the sole upper compacting pressure in a direction substantially perpendicular to the plane of the sole bottom, and means coincidentally to cause the sole pressing member to exert yielding pres- 100 105 110 115 120 125

sure against the sole and last to hold them against lengthwise displacement by the closing-over thrust of the wipers.

86. A machine of the class described having, in combination, end wipers, a member arranged to hold the sole edge down on the last bottom at the extreme end of the shoe, said member also forming a gage arranged to engage the sole to determine the elevation of the sole relatively to the plane of closing movement of the wipers, means to support a last and shoe with the edge of the sole in co-operative engagement with said gage member and with the sole approximately in the plane of closing movement of the wipers, means to close the wipers, and means to move said sole gaging and holding member out of the path of the closing wipers as the wipers advance over the edge of the sole.

87. A machine of the class described having, in combination, end wipers, a finger having a lower edge curved substantially to conform to the curvature of the extremity of a last and arranged to hold the edge of the sole at said extremity down against the last bottom, said finger also forming a gage arranged determinately to engage the sole to determine the elevation of the sole relatively to the plane of closing movement of the wipers, means to support a last and shoe with the edge of the sole in co-operative engagement with said finger and with the sole approximately in the plane of closing movement of the wipers, means to close the wipers, and means to lift said sole gaging and holding finger above the path of the closing wipers as the wipers advance over the edge of the sole.

88. A toe lasting machine having, in combination, end wipers, a finger having a lower sole engaging edge curved substantially to conform to the curvature of the toe end of a last at its extremity and arranged to hold the edge of the sole at said extremity down against the last bottom, said finger also forming a gage arranged to engage the feather and lip of the sole at said extremity of the last to determine the elevation of the sole relatively to the plane of closing movement of the wipers, means to support a last and shoe with the sole in co-operative engagement with said gage finger and with the sole approximately in the plane of closing movement of the wipers, means to close the wipers over the toe end of the sole, and means to lift said finger above the path of the closing wipers as the wipers advance over the edge of the sole.

89. A machine of the class described having, in combination, end wipers, a hold-down member and an opposed last supporting member relatively movable to clamp between them a last with a sole and shoe upper in co-operative relation to the wipers, a

presser member positioned adjacent to said hold-down arranged to engage the edge of the sole at the extremity of the last to hold said end of the sole down on the last bottom and forming a gage against which the sole is held, means to effect downward movement of the hold-down and presser member and coincident upward movement of the last supporting member to clamp the last between them with the sole engaging said presser member and positioned thereby approximately in the plane of closing movement of the wipers, means for closing the wipers over the last bottom, and means for lifting the presser member out of the path of the closing wipers as they advance over the edge of the sole.

90. A toe lasting machine having, in combination, end wipers, a hold-down member and an opposed toe supporting member relatively movable to clamp between them a last with the toe end of the sole and shoe upper in co-operative relation to the wipers, a presser member positioned adjacent to said hold-down arranged to engage the edge of the sole at the extremity of the toe to hold said end of the sole down on the last bottom and forming a gage against which the toe end of the sole is held, means to effect downward movement of the hold-down and presser member and coincident upward movement of the toe supporting member to clamp the last between them with the sole engaging said presser member and positioned thereby approximately in the plane of closing movement of the wipers, means for closing the wipers over the toe end of the last bottom, and means for lifting the presser member out of the path of the closing wipers as they advance over the edge of the sole.

91. In a lasting machine, end embracing wipers, means to hold the wipers open and out of engagement with the shoe, and means to grip and pull the upper at the end of the shoe outwardly from the last against and over the edges of the open wipers preparatory to closing the wipers.

92. In a toe lasting machine, toe embracing wipers, wiper operating means constructed to hold the wipers initially open and out of engagement with the shoe, power operated means to grip and pull the edge of the upper at the toe end of the shoe outwardly from the last against the edges of the open wipers, and means for causing the wiper operating means subsequently to close the wipers over the edge of the shoe sole.

93. In a toe lasting machine, toe embracing wipers, wiper operating means constructed to hold the wipers initially open and out of engagement with the shoe, power operated means to grip and pull the edge of the upper at the toe end of the shoe outwardly from the last against the edges of the open wipers, and means for causing the wiper operating means subsequently to close the wipers over the edge of the shoe sole.

wiper operating means subsequently to close the wipers over the edge of the shoe sole and the gripping means to maintain outward pull on the upper as the wipers close over 5 the sole edge.

94. In a toe lasting machine, toe embracing wipers, a last and shoe support, grippers arranged to engage the edge of the shoe upper at the toe end of a supported shoe, 10 and power operated mechanism for effecting relative movement of said parts, to cause the grippers to pull the edge of the upper outwardly from the last against the edges of the open wipers, and subsequently to close 15 the wipers over the margin of the sole without preliminary pressure against the last and upper above the plane of the bottom of the sole.

95. In a lasting machine, end embracing 20 wipers, power operated mechanism for pulling the upper at one end of the shoe outwardly from the last against the edges of the open wipers, and means to hold the wipers open and out of pressure applying 25 relation to the end of the last during said pulling movement and subsequently to advance the wipers over the edge of the sole and coincidently to cause the wipers to exert compacting pressure against the inwiped 30 upper and the sole.

96. In a lasting machine, end embracing wipers, wiper operating means constructed to hold the wipers in open position out of contact with the upper above the plane of 35 the sole, means for pulling the edge of the upper projecting beyond the sole outwardly from the sides of the last against the edges of the open wipers, and means for subsequently causing the wiper operating means 40 to close the wipers over the edge of the sole without preliminary pressure against the upper above the plane of the sole and with the upper tensioned against the edges of the closing wipers and for causing the sole 45 and inwiped upper to be pressed against the closing wipers.

97. In a machine of the class described, the combination with last and upper positioning means, of end embracing wipers movable 50 from an idle position comparatively remote from the end face of the last to wipe the margin of the upper inwardly over the bottom of the last, and means for pulling the upper outwardly away from the end face of 55 the last and over the edges of the wipers before the wipers begin their operative inward movement.

98. In a machine of the class described, the combination with last and upper positioning 60 means, of end embracing wipers mounted for closing movement inwardly over the bottom of the last from an idle position comparatively remote from the lateral periphery of the last, and means for pulling the upper 65 outwardly over the edges of said wipers be-

fore they begin to close and for maintaining such outward pull as the closing movement of the wipers progresses.

99. In a machine of the class described, the combination with last and upper positioning 70 means, of end embracing wipers, means for gripping the margin of the upper, and means for operating said gripping means and wipers in time relation to pull the upper outwardly away from the lateral periphery of 75 the last and over the edges of the wipers and to cause the wipers by movement toward the end of the last substantially in the plane of the bottom face of the sole of the shoe to draw the upper inwardly against the lateral 80 periphery of the last and then to wipe it over the bottom of the sole.

100. In a machine of the class described, the combination with last and upper positioning means, of end embracing wipers, 85 means for gripping and pulling the upper outwardly away from the lateral periphery of the last at the end and at the opposite sides of the end portion of the last and against the edges of the wipers while the 90 wipers are so positioned as to permit the upper between their edges and the last to be spaced from the lateral periphery of the last, and means for advancing the wipers 95 and closing them inward laterally of the shoe while the outward pull on the upper is maintained.

101. In a machine of the class described, the combination with last and upper positioning means, of end embracing wipers, a 100 gripper for engaging the upper at the end of the last, additional grippers for engaging the upper at the corners of the end portion of the last, means for operating said grippers to pull the upper forwardly at the end 105 and diagonally outward at the corners of the last away from the lateral periphery of the last and over the edges of the wipers, and means for subsequently closing the wipers inwardly toward and over the edge of the 110 last bottom while the forward and outward pull on the upper is maintained.

102. In a machine of the class described, the combination with last and upper positioning means, of end embracing wipers, 115 means for pulling the upper outwardly from the lateral periphery of the end portion of the last while the wipers are positioned comparatively remote from the end face of the last, and means for effecting relative movement of said positioning means and wipers in a direction transverse to the plane of the last bottom with the wipers in wiping engagement with the tensioned upper while the upper between the wiper edges and the last is 120 thus held outwardly from the last.

103. In a machine of the class described, the combination with last and upper positioning means, of end embracing wipers, 130 means for gripping and pulling the upper

outwardly from the lateral periphery of the end portion of the last and over the edges of said wipers with the wipers positioned between the planes of the bottom and top faces 5 of the end portion of the last and comparatively remote from the end face of the last, and means for effecting relative movement of said positioning means and wipers in a direction transverse to the plane of the shoe 10 bottom while the upper between the edges of the wipers and the last is thus pulled outwardly to cause the wipers to unwipe the upper round the lateral periphery of the last without inward pressure of the wipers 15 against the last.

104. In a machine of the class described, the combination with means for positioning a last and a turn shoe upper and sole, of end embracing wipers, means for gripping and 20 pulling the upper outwardly from the end face of the last with the wipers positioned between the planes of the bottom and top faces of the end portion of the last and comparatively remote from the end face of the 25 last, and means for effecting relative movement of said positioning means and wipers in a direction transverse to the plane of the sole to cause the wipers to unwipe the upper while the upper is thus held outwardly and 30 while the wipers are maintained at a sufficient distance from the end face of the last to avoid substantial pressure against the edge of the sole.

105. In a machine of the class described, 35 the combination with last and upper positioning means, of end embracing wipers, means for gripping and pulling the upper outwardly away from the lateral periphery of the last and over the edges of said wipers, 40 means for moving the last relatively to the wipers and in a direction to cause said gripping means further to tension the upper while pulling it outwardly from the last, and to cause the wipers to smooth the tensioned upper, and means for subsequently 45 operating the wipers to draw the upper against the lateral periphery of the last and to wipe it inwardly over the bottom of the last.

106. In a machine of the class described, 50 the combination with last and upper positioning means, of end embracing wipers, means for gripping and pulling the upper outwardly from the end face of the last 55 while the wipers are positioned between the planes of the bottom and top faces of the end portion of the last and at such a distance from the end face of the last as to permit the upper between said face and the 60 wiper edges to be held out of contact with said face, means for effecting relative movement of said positioning means and wipers to cause the wipers to wipe the upper toward the plane of the last bottom while it is held 65 away from the end face of the last, and

means for subsequently operating the wipers to draw the upper against said face and wipe it inward over the bottom of the last.

107. In a machine of the class described, 70 the combination with last and upper positioning means, of grippers for engaging the margin of the upper at opposite sides of an end portion of the last, said grippers being mounted to swing outwardly from the last about axes extending in transverse relation 75 to the plane of the shoe bottom and disposed substantially at the rear of their gripping faces in the direction of the heel end of the shoe, and means for imparting to the grippers operative swinging movement about 80 said axes to pull the upper.

108. In a machine of the class described, 85 the combination with last and upper positioning means, of grippers for engaging the margin of the upper substantially at the corners of one end of the last, said grippers being mounted to swing outwardly about axes extending in transverse relation to the plane of the shoe bottom and disposed at the rear of their gripping faces and farther outwardly from the shoe than said faces, and means for imparting to the grippers operative swinging movements about said axes to 90 pull the upper.

109. In a machine of the class described, 95 the combination with last and upper positioning means, of grippers arranged to engage the margin of the upper substantially at the corners of one end of the last, said grippers being mounted for operative swinging movement about axes extending in transverse relation to the plane of the shoe bottom and disposed substantially at the rear of their gripping faces in the direction of the heel end of the shoe, said grippers being 100 adjustable about axes disposed substantially at the front ends of their gripping faces.

110. In a machine of the class described, 110 the combination with last and upper positioning means, of grippers for engaging the upper substantially at the corners of one end of the last, supports for said grippers mounted for operative swinging movement about axes extending in transverse relation to the plane of the shoe bottom and located 115 at the rear of said grippers in the direction of the heel end of the shoe, and gripper carriers on said supports upon which said grippers are mounted, said gripper carriers being mounted to swing adjustably about 120 different axes than said supports.

111. In a machine of the class described, 125 the combination with last and upper positioning means, of grippers for engaging the upper at the opposite sides of an end portion of the last, gripper supports mounted for operative swinging movement laterally outward from the last, said supports being provided with arc-shaped guideways, and gripper carriers on said supports on which 130

said grippers are mounted, said carriers being adjustably movable along said guideways.

112. In a machine of the class described, the combination with last and upper positioning means, of grippers for engaging the upper at the opposite sides of an end portion of the last, supports for said grippers mounted for operative swinging movement laterally outward from the last, gripper carriers mounted on said supports and movable relatively thereto to position the grippers in different angular relations to the longitudinal median line of the shoe, and mechanism comprising spring held latches for retaining said gripper carriers in different adjusted positions.

113. In a machine of the class described, the combination with last and upper positioning means, of a gripper for engaging the upper at the end of the last, additional grippers for engaging the upper substantially at the corners of the end of the last, means for moving said end gripper forwardly from the end of the last to pull the upper, and means for swinging said additional grippers diagonally outward from the corners of the last about axes extending in transverse relation to the plane of the last bottom.

114. In a machine of the class described, the combination with last and upper positioning means, of a gripper for engaging the upper at the end of the last, additional grippers for engaging the upper substantially at the corners of the end of the last, operating means movable lengthwise of the last to impart a forward upper pulling movement to said end gripper, and connections between said lengthwise movable means and the corner grippers to move them diagonally outward from the corners of the last.

115. In a machine of the class described, the combination with last and upper positioning means, of a gripper for engaging the upper at the end of the last, additional grippers arranged to engage the upper substantially at the corners of the end of the last and mounted to swing laterally outward to pull the upper, operating means movable lengthwise of the last to impart a forward pulling movement to said end gripper, and yielding connections between said operating means and the corner grippers for swinging them outwardly.

116. In a machine of the class described, the combination with last and upper positioning means, of grippers for engaging the upper at opposite sides of an end portion of the last, means for adjusting said grippers bodily toward or from each other for shoes of different widths, and means for adjusting said grippers also in different angular relations to the longitudinal median line of the last.

117. In a machine of the class described,

the combination with last and upper positioning means, of grippers for engaging the upper at opposite sides of an end portion of the last, means for adjusting said grippers bodily toward or from each other for 70 shoes of different widths, and means for adjusting said grippers also angularly about axes extending in transverse relation to the plane of the shoe bottom and located substantially at the front ends of their gripping 75 faces.

118. That improvement in methods of making shoes which consists in gripping the margin of an upper on a last and pulling the upper outwardly from the lateral periphery of the last, and while the upper is thus held outwardly under tension wiping the upper over the lateral periphery of the last in a direction transverse to the plane of the shoe bottom in such manner as to 80 avoid pressing the upper inwardly against the last.

119. That improvement in methods of making shoes which consists in gripping the margin of an upper at the toe end of a last 90 and pulling the upper outwardly from the end face of the last, and then wiping the portion of the upper extending round the toe in a direction transverse to the plane of the shoe bottom while maintaining said portion 95 of the upper spaced from the end face of the last.

120. That improvement in methods of making turn shoes which consists in gripping the margin of upper materials round 100 the end of a last and pulling the materials outwardly from the end face of the last, and while the upper materials are thus held under tension outwardly from the end face of the last wiping said materials in a direction transverse to the plane of the shoe bottom and in such relation to the last as to avoid pressure against the marginal edge of the sole of the shoe in wiping the materials across the plane of said edge.

121. That improvement in methods of making shoes which consists in gripping the margin of an upper at the toe end and the corners of the toe of a last and pulling the upper outwardly from the lateral periphery 115 of the last round the toe, and then embracing the upper round the toe and wiping it in a direction transverse to the plane of the shoe bottom while maintaining the upper in spaced relation to the end face of the last.

122. That improvement in methods of making shoes which consists in gripping the margin of an upper round the toe of a last and pulling the upper outwardly from the end face of the last over the edges of end 125 embracing wipers engaging the upper in a plane between the bottom and top faces of the last, and then by the aid of said wipers wiping the upper in a direction transverse to the plane of the shoe bottom while main- 130

taining the portions of the upper between the wipers and the last in spaced relation to the end face of the last.

123. That improvement in methods of 5 making shoes which consists in gripping the margin of an upper at the corners of the toe of a last over a substantial area lengthwise of the last and pulling the gripped portions of the upper both lengthwise and 10 laterally of the last with less lateral pull on the rear portions of the gripped upper than on portions nearer the toe end of the shoe, and subsequently working the upper inwardly over the bottom of the last.

124. That improvement in methods of 15 making shoes which consists in gripping the margin of an upper at the toe end and at the corners of the toe of a last and pulling the upper forwardly at the toe end and the corners with a lateral outward pull at the corners progressively decreasing in extent from the front to the rear ends of the corner portions of the upper, and subsequently working the margin of the upper inwardly over the bottom of the last. 20

In testimony whereof I have signed my name to this specification.

CHARLES F. PYM.

Certificate of Correction.

It is hereby certified that in Letters Patent No. 1,413,613, granted April 25, 1922, upon the application of Charles F. Pym, of Lynn, Massachusetts, for an improvement in "Lasting Machines," errors appear in the printed specification requiring correction as follows: Page 2, line 96, for the misspelled word "whch" read *which*; page 3, line 121, for the word "of" read *or*; page 8, line 9, strike out the words "of other parts", and line 10, after the word "to" insert the words *other parts of*; page 13, line 95, claim 10, after the word "side" and before the comma insert the words *of the toe*; page 14, line 80, claim 17, strike out the word "vertical"; page 22, line 43, claim 68, for the word "above" read *aligned with*; and that the said Letters Patent should be read with these corrections therein that the same may conform to the record of the case in the Patent Office.

Signed and sealed this 29th day of August, A. D., 1922.

[SEAL.]

KARL FENNING,

Acting Commissioner of Patents.
